ZERO-SETTING DEVICE FOR REGISTERS

Kenly C. Bugg, Fort Wayne, Ind.

Application April 22, 1940, Serial No. 330,867

33 Claims. (Cl. 235—144)

1

This invention pertains to registering mechanism.

It is an object of this invention to provide registering mechanism provided with a plurality of banks of indicating means operated through substantially identical mechanism.

Another object of this invention is to provide registering mechanism having a set-back device adapted for automatic or manual reset.

Still another object of this invention is to provide registering mechanism provided with power drive means.

Yet another object of this invention is to provide power driven registering mechanism wherein the indicating means may be adapted to either lead the control means, or the power drive may act as boosting means for the control means.

A further object of the invention is to provide registering mechanism which may readily be reset to zero at any time but one wherein the operating means starts forward immediately upon operation of the control or operating means.

A still further object of the invention is to provide registering mechanism wherein the effect of backlash is eliminated.

A yet further object of the invention is to provide braking means for a rotatable member effective to brake said member immediately upon the tendency of said member to rotate in one direction, but which permits said member to freely rotate in the opposite direction immediately upon any tendency to rotate in said last named direction.

Another further object of the invention is to provide registering mechanism having means for setting said registering mechanism to a predetermined position so constructed and arranged that no torque is put on the calibrating (i. e., initial or fraction) indicating means.

A different object of the invention is to provide registering mechanism which is inexpensive to make and maintain, and is comparatively simple so that it may be susceptible of use in a computing head of a liquid dispensing apparatus. Thus extreme accuracy must exist as in this country only three cubic inches of error plus or minus is permitted in five gallons (1155 cu. in.) and this error must take care of any meter inaccuracy.

A still different object of this invention is to provide registering mechanism wherein the inertia of the transfer mechanism is eliminated.

A yet different object of this invention is to provide a power driven registering mechanism wherein both the indicating means and the control mechanism is power driven.

10 A further different object of this invention is to provide registering mechanism adapted to be associated with variating means and a meter of a liquid dispensing apparatus, said registering mechanism being power driven so that the meter and variator merely control said registering mechanism, and do not drive or push said registering mechanism.

Another different object of this invention is to provide registering mechanism which will accurately indicate the flow through a low head meter, as no load is placed on said meter.

15 A still different object of this invention is to provide registering mechanism for a computing head of a liquid dispensing apparatus which may be either a motor power driven registering mechanism which leads the variator of said head, or a meter power driven registering mechanism which takes the load off the control mechanism 20 for the indicating means of the registering mechanism.

Another object of the invention is to provide registering mechanism wherein the transfer means is ineffective during the resetting operation, but is constantly in engagement for operation with this associated mechanism.

Another object is to provide registering mechanism having reset means which is serial in its operation, insuring that all members of the indicating means reach zero, as the respective indicating means is not reset to zero until after the calibrating elements (initial indicating means) reach zero.

Another object is to provide registering mechanism having only a single element to engage to reset a plurality of banks of wheels or indicating means, or control mechanisms therefor, as distinguished from a registering mechanism wherein the same number of units as are in the indicating

40 means must be meshed for each pair of banks of indicating means (numeral wheels) for resetting, and then must be disengaged after reset.

Another object is to provide registering mechanism having control shafts wherein each control 45 shaft is zeroized independently of the other, thus making it possible to use a numeral wheel type of register wherein the reset crank can be rotated three or less turns to zeroize the numeral wheels. This distinguishes from the registering mechanism now in use wherein the release of the control shafts of the indicating means (numeral wheels) must be simultaneous, and the setback cycles for both banks of indicating means (money and amount) must be simultaneous, making it 50 necessary to use more than one and less than two

turns of the reset shaft. Thus, in the registering mechanism which illustrates this invention it is not necessary to synchronize movements of the control shafts, nor is it necessary that there be any relation between said shafts in resetting.

Another object is to provide registering mechanism having reset means so constructed and arranged that disengaging of the mechanism for the indicating means need not be effected simultaneously.

Another object is to provide registering mechanism having reset means permitting setback to be accomplished without any friction driving mechanism so that the reset will operate under any conditions. Thus, when the force needed to reset the registering mechanism is exceeded, as when the reset mechanism operates in a reset direction after the register has been zeroized, the reset becomes inoperative without any additional torque or friction being applied to the registering mechanism or control means therefor. With such reset mechanism for such registering mechanism, no increase or torque or friction is introduced during reset, that is, it is always a constant as applied to the indicating means or control means.

Another object is to provide registering means having a plurality of banks of indicating means, such as numeral wheels, having a common reset element which sets back the control elements for the numeral wheels in series, as distinguished from setting back said elements in parallel.

Another object is to provide registering mechanism wherein power driven numeral wheels are provided which are not pinned or otherwise fixed to their supporting shafts, being positioned thereon by frictionally held pawls engaging in suitable tracks or grooves provided in the shaft, thus insuring their position without the use of other positioning means.

Another object is to provide power driven registering mechanism wherein the necessity of timing the operating elements is eliminated to a high degree, inasmuch as the driving elements are self-aligning immediately upon assembly.

Another object is to provide registering mechanism wherein the indicating elements, such as numeral wheels, are chain driven, thus making it possible to locate the indicating means at any desired position with respect to the driving means therefor without the necessity of inserting an expensive gear train.

Another object is to provide registering mechanism wherein certain driving elements are power driven by chains during reset, making it possible to keep the chains for the visible registering means taut at all times in the direction of registering progression.

Another object is to provide registering mechanism having reset means therein so constructed and arranged that the calibrating units or driving mechanism are held by dead stop locking pawls so that no external efforts, such as jarring, can displace the driving mechanism, and only serving or forward operation can render the pawls inoperative.

Another object is to provide registering mechanism having reset means therein so constructed and arranged that the mechanisms for the gallons and money banks of wheels are independent, each to the other, of the exact starting or stopping positions. Also, no consideration need be given to over-rotation of the reset crank, as it has no timed relation on the start of the reset cycle.

Another object is to provide registering mechanism provided with a power drive for serving operation, and an independent power drive for reset operation.

Another object is to provide clutch mechanism which is positive in its forward drive, yet may be readily and quickly broken or declutched, as for reverse rotation, the included angle of the clutch faces driving and driven elements being between five and six degrees.

Another object is to provide registering mechanism wherein the indicating means is reset through less than three hundred and sixty degrees.

With these and various other objects in view, the invention may consist of certain novel features of construction and operation as will be more fully described and particularly pointed out in the specification, drawings and claims appended hereto.

In the drawings, which illustrate embodiments of the device, and wherein like reference characters are used to designate like parts—

Figure 1 is a top plan view of one form of registering mechanism embodying the invention;

Figure 2 is a fragmentary side elevation of the registering mechanism illustrated in Figure 1, the same looking upwardly as viewed in said figure (or toward the left as viewed in Figure 4);

in Figure 30, the section being taken substantially in the plane as indicated by the line 30A—30A of Figure 30;

Figure 31 is an enlarged plan view of a co-operating portion of the reset mechanism, the same being taken substantially in the plane indicated by the line 31—31 of Figure 29;

Figure 32 is a top plan view of another form of meter power drive mechanism embodying the invention;

Figure 33 is a side elevation of the meter power drive computing head illustrated in Figure 32, the same showing the application thereto of a side variator;

Figure 34 is an elevation looking toward the numeral wheels of the meter power drive head illustrated in Figure 32;

Figure 35 is an elevation partly in section, taken substantially in the plane as indicated by the line 35—35 of Figure 32, but omitting the numeral wheel drive from the driving mechanism;

Figure 36 is an elevation partly in section, the same being taken substantially in the plane as indicated by the line 36—36 of Figure 32, but showing the gear box in section and showing the numeral wheel drive from the driving mechanism in the plane as shown in line 35—35;

Figure 37 is an enlarged sectional elevation taken substantially in the plane of the longitudinal center line of the drive mechanism for the top or money bank of numeral wheels of the meter power drive mechanism illustrated in Figure 32;

Figure 38 is a sectional elevation taken substantially in the plane as indicated by the line 38—38 of Figure 37;

Figure 39 is an enlarged sectional elevation taken substantially in the plane as indicated by the line 39—39 of Figure 37;

Figure 40 is an enlarged transverse sectional elevation taken substantially in the plane as indicated by the line 40—40 of Figure 37;

Figure 41 is an enlarged sectional elevation taken substantially in the plane as indicated by the line 41—41 of Figure 37;

Figure 42 is an enlarged sectional elevation taken substantially in the plane as indicated by the line 42—42 of Figure 32;

Figure 43 is an enlarged sectional elevation through a portion of the whole mechanism illustrated in Figure 42, showing the same in "0" or whole position;

Figure 44 is an enlarged sectional elevation through a portion of the zeroizing mechanism for the meter power drive illustrated in Figure 32;

Figure 45 is an enlarged sectional elevation, a portion of the operating mechanism showing the clutch in engaged position;

Figure 46 is an enlarged sectional elevation taken substantially in the plane as indicated by the line 46—46 of Figure 45;

Figure 47 is an enlarged sectional elevation taken substantially in the plane as indicated by the line 47—47 of Figure 45;

Figure 48 is an enlarged fragmentary elevation of the ratchet permitting power drive by the meter and by the reset;

Figure 49 is a plan view, partly in section, showing the price synchronizing means, the same being taken substantially in the plane as indicated by the line 49—49 of Figure 36;

Figure 50 is a transverse sectional elevation taken substantially in the plane as indicated by the line 50—50 of Figure 32 showing the pawl

connection to the numeral wheel shafts for the reset power drive;

Figure 51 is a sectional elevation corresponding to Figure 37 showing a modification wherein the numeral wheels are reset through rotation of less than 360°;

Figure 52 is an enlarged elevation of the stop for a portion of the mechanism shown in Figure 51, the same being taken substantially in the plane as indicated by the line 52—52 of Figure 51, but with certain parts omitted.

Registering mechanism—Figures 1 to 15 inclusive

Referring first of all more particularly to the registering mechanism illustrated in Figures 1 to 15 inclusive, said registering mechanism consists essentially of the spaced side frames 50 and 52 providing supports for the brackets 54 and 56 for supporting the upper and lower numeral wheel shafts. Inasmuch as the upper and lower numeral wheel arrangements are identical for each side of the registering mechanism and identically arranged, only the upper pair of said arrangements is illustrated. Said shafts are shown at 58 and 60.

Numeral wheel mounting

The registering mechanism shown is particularly adapted for a computing head of a liquid dispensing apparatus wherein the upper bank of numeral wheels is adapted to indicate the price of the liquid dispensed, while the lower bank is adapted to indicate the amount or gallons of liquid dispensed. It is of course understood that other numerical characteristics may be indicated, and the register is adaptable for other uses. In the embodiment shown, the numeral wheel 62 for showing dollars or hundreds is rotatably mounted on the shaft 60 and the sprocket 64 is non-rotatably provided on said numeral wheel. The numeral wheel 66 for indicating tens is rotatably mounted on the shaft 60 and is non-rotatably provided with the sprocket 68. The numeral wheel 70 for indicating cents or units is also rotatably mounted on the shaft 60 and is non-rotatably provided with the sprocket 72.

On the opposite side of the registering mechanism there is provided the dollars or hundreds numeral wheel 74, the tens numeral wheel 76, and the cents or units units numeral wheel 78. The cents numeral wheel 78 is non-rotatably mounted on the sleeve 80 which is rotatably mounted on the shaft 58 and extends transversely of said shaft, being non-rotatably provided with the sprocket 82 aligned in the vertical plane of the sprocket 72. The dollars numeral wheel 74 is non-rotatably mounted on the sleeve 84 rotatably mounted on the sleeve 80, and said sleeve 84 extends toward the bracket 54 and is non-rotatably provided with the sprocket 86 aligned with the sprocket 64. The tens numeral wheel 76 is rotatably mounted on the sleeve 84 and is non-rotatably provided with the sprocket 88 aligned with the sprocket 68.

The dollars numeral wheels 62 and 74 on opposite sides of the registering mechanism are connected by means of the chain 90 which engages the sprockets 64 and 86, said chain being operated by the sprocket 92 of the money power drive mechanism indicated generally at 94. The tens numeral wheels 66 and 76 on opposite sides of the registering mechanism are adapted to be connected by the chain 96 engaging the sprockets 68 and 88 and adapted to be operated by means of the sprocket 98 of the money power drive mech-

anism 94. The units or cents numeral wheels 70 and 78 on opposite sides of the registering mechanism are adapted to be connected through the sprockets 72 and 82 by means of the chain 100 actuated by the sprocket 102 of the money power drive mechanism 94.

The amount numeral wheels on the shafts below the shafts 58 and 60 are similarly connected to their respective power drive mechanism indicated generally at 104 (Figure 4), through the sprockets 106, 108 and 110 which are similar to the sprockets 92, 98 and 102, respectively. In Figure 4 the lower amount or gallons wheels 112, 114 and 116 are shown carried by the lower shaft corresponding to shaft 58 and rotatably mounted thereon in a manner similar to the wheels 78, 76 and 74, and being connected to the sprockets 106, 108 and 110 in the same manner as sprockets 82, 88 and 86 are connected to sprockets 102, 98 and 92. Also, it is understood that there is a bank of amount numeral wheels below the numeral wheels 62, 66 and 70, that is mounted similarly to said last named numeral wheels, and similarly connected to its power drive mechanism 104.

25

Motor drive

The motor 118 is supported between the spaced frames 50 and 52 as at 119, and is preferably of the reversible type, driving in one direction, such as counterclockwise as viewed in Figure 2, to furnish the power drive, and driving clockwise, as viewed in Figure 2, for resetting. The switch 120, to be described more particularly later, is adapted to control the direction of operation of the motor. The motor drive shaft 122 is provided with the pinion 124 meshing with the gear 126 pivoted to the frame member 52 as at 127, the gear 126 being non-rotatably provided with the pinion 128. The pinion 128 meshes with the gear 130 pivoted to the side frame 52 as at 132, being provided with the drum 134. The flexible belt 136 is wound completely around the drum and passes over the upper pulley 138 and downwardly to be received by the lower pulley 140 and thence upwardly to the drum 134. The pulleys 138 and 140 are non-rotatably mounted on the respective power drive shafts 142 and 144, the shafts between the plates 50 and 52 being identical.

Reset mechanism

The shafts 142 and 144 are provided with the reset members 146 and 148, said members being non-rotatably mounted on said shafts and being provided with the inner ball engaging plane surfaces 150 and 152. The stationary reset members 154 and 156 are fixedly mounted on the bracket 52 and are journaled for receiving the shafts 142 and 144 respectively. The members 154 and 156 are provided with the spiral tracks 158 and 160 facing the plane surfaces 150 and 152 of the rotary reset members 146 and 148. The spiral tracks are adapted to receive the floating balls 162 and 164. The spiral tracks are so arranged for resetting operation that the balls are adapted to travel in a clockwise direction as viewed in Figure 5 so that they walk inwardly where they ultimately are received in the apertures 166 and 168 which extend through the members 154 and 156, so that when the balls are received in said apertures they pass inwardly of the members 154 and 156 to be received in the downwardly directed tracks 170 and 172 on the opposite sides of the members 154 and 156 from the spiral tracks 158 and 160.

75

The balls are then free to return to their starting positions in the spiral tracks 158 and 160 through other apertures 174 and 176. In order to prevent the ball 162 from returning to its starting point prior to the time that the ball 164 returns to its starting point and thus causing a new cycle of resetting to be set up for the power drive mechanism 94, the track 158 is provided with a recess 177 offset from the aperture 166. The recess 177 is provided with the leaf spring 179, the fastened end of which is secured as at 181 (Fig. 5A) to the platform 183. The recess 177 is deeper than the track 158 and the platform 183 is below said track whereby the spring is below said track but above the bottom of recess 177 and slightly above track 185 leading to aperture 166. Thus the spring urges the ball toward the rotating plane member 146 and prevents the ball rolling into the track 185. Therefore, when the ball 162 reaches the recess 177 it will be received on the leaf spring and trapped in said recess 177. When, however, the ball 164 has reached its aperture 168 and the shaft 144 has moved toward the left as viewed in Figure 4, the switch 120 will be reversed to reverse the motor 118, as herein described, causing the plane member 146 to be rotated in a counterclockwise direction, as viewed in Figs. 5 and 5A, to move the ball 162 from the recess 177 to track 185 and to the aperture 166 to permit said ball to return to its starting point through the track 170 and the aperture 174.

The spiral tracks 158 and 160 are provided with sloping portions from the apertures 174 and 176 so that when the members 146 and 148 are rotated in a resetting direction, namely, clockwise as viewed in Figure 5, the balls 162 and 164 will be caused to walk up the sloping portions from the deep portions such as shown at 178 in Figure 6, to the shallower portions 180 as shown in that figure, which will cause a separation between the members 146 and 154, and 148 and 156, which in turn will cause a motion of translation of the shafts 142 and 144 toward the right. However, due to the deep portions of the spiral tracks 158 and 160, when the motor is driving in a counterclockwise direction there will be no wear on the balls.

Power drive mechanism

The shafts 142 and 144 are identical between the side frames 50 and 52, so unless otherwise specifically designated, the following description applies to both of said shafts. The shaft 142 is provided with the reduced portions 182 provided with the spaced shoulders 184 and 186 (Figure 10) disposed 180° apart, the shoulders being disposed to be effective when the shaft 142 is rotated in a driving direction. The opposite portions of the shaft are gradually sloping as at 188 to act as inclined planes for moving the roller 190 upwardly against the spring 192. The spring and roller are mounted in a cylindrical portion or hub 194 of the sprocket 102, and are retained thereon by means of the retaining member 196. The shafts are also provided with the reduced portion 198 provided with the shoulder 200 (Figure 11) also disposed to be effective in a driving direction, the back of said shoulder being sloping as at 202 to provide an inclined plane for engaging the ball 204 to move said ball against the spring 206, the ball and spring being mounted in the cylindrical portion or hub 208 of the sprocket 98. The ball and spring are retained by the retainer member 210.

Similarly, a reduced portion 212 of the same type as the reduced portion 198 is provided with the shoulder 214 similar to the shoulder 200, and effective to cooperate with the ball 216 urged toward the reduced portion by the spring 218 and retained in the cylindrical portion or hub 220 of the sprocket 92 by means of the retainer 222.

Switch control

The shafts 142 and 144 extend through the frame 50, being journaled therein as at 224 and 226, and are urged toward the left as viewed in Figure 4 by means of the springs 228 and 230. The spring 228 is seated at its inner end against the journal and at its outer end against the collar 232 on the shaft 142. The spring 230 is seated at its inner end against the journal 226, and at its outer end against the shoulder 234 provided on the switch control member 236. The outer end of the switch control member (Figures 13-15) is provided with the head 238 having the inner bevelled surface 240 and the outer bevelled surface 242, the surface 240 being adapted to engage the inner leg 244 of the latch member or lever 246, said member being pivoted as at 248 to the support 250 through which the journal member 252 of the switch control knob 254 extends.

An oppositely disposed latch member or lever 256 is also pivoted as at 248 and is provided with the outer leg 258 adapted to be engaged by the bevelled surface 242, said lever 256 being provided with the inner leg 260 similar to the upwardly extending leg 262 of the lever 246. The legs 244 and 258 are urged toward each other by means of a spring 264. The journal member 252 is provided with the rotatable switch shaft 266 journaled as at 268 to the switch 120, being provided with the operating arm 270 extending into the switch and being normally in closed position to operate the motor in a counterclockwise direction, being urged into that position by means of the spring 272.

The member 252 is provided with the slot 274, said slot being adapted to form locking means with the respective legs 260 and 262. When the motor is operated in a counterclockwise direction, that is, when the registering mechanism is conditioned for registering, the shafts 142 and 144 will be in a position such as shown in Figure 6, in which case, as shown in Figures 13 and 14, the bevelled surface 242 will engage the leg 258 of the lever 256. The legs 262 and 260, however, will not be in the slot 274 as it will be in the position as indicated in Figure 15. The knob 254 can then be rotated to close the switch 120 in reversing position, in which position the leg 262 will engage in the slot 274, locking the switch in reversing position. As the motor operates the shaft 144 in a reversing direction, the shaft 144 will move toward the right, as viewed in Figure 13, by movement of the ball 164 to separate the members 148 and 156 which will cause the bevelled surface 240 to move the leg 244 to permit the spring 272 to move the switch 270 toward closed forward position. But this motion of the switch will be arrested by engagement of the leg 260 in the slot 274, as shown in dotted lines in Figure 14. However, when the reset is complete and the ball 164 enters the aperture 168, the spring 230 will move the shaft 144 to the left as viewed in Figure 13, where it moves the leg 258 to disengage the leg 260 from the slot 274 to permit the spring 272 to move the switch 120 to its closed forward position for registering operations. It

is noted that the shaft 144 never operates the switch from reversing to forward position until after the spring 228 has moved the shaft 142 to its left position, i. e., after reset of the upper numeral wheels.

Control connection to power drive mechanism

Where the registering mechanism is to be used in a computing head, it is of course adapted to be controlled by variating mechanism such as shown in applicant's Patent No. 2,323,373, granted July 6, 1943. The upper (money) power drive mechanism 94 is adapted to be operated through the variator, the variator being connected to the bevel gear 276 non-rotatably mounted on the shaft 278. The shaft 278 is provided with the gear 280 meshing with the gear 282 pivoted as at 284 to the side frame 52. The gear 282 meshes with the gear 286 pivoted to the side frame 52 as at 288, being provided with the bevel gear 290 meshing with the bevel gear 292. The bevel gear 292 is non-rotatably mounted on the shaft 294 journaled as at 296 and 298 to the side frame 52, and said shaft is provided with the bevel gear 300 meshing with the bevel gear 302 which is pivoted as at 304 to the side frame 52, and is non-rotatably provided with the gear 306 meshing with the gear 308 pivoted as at 310 to the frame 52. The gear 308 meshes with the gear 312 non-rotatably provided on the cylindrical member or clutch member 314.

The meter shaft, in the case of a liquid dispensing apparatus, is connected to the bevel gear 316 non-rotatably mounted on the shaft 318 and directly drives said shaft 318, though as a matter of engineering the meter shaft may drive the shaft 318 by means of a drive through the variator as described in said Patent No. 2,323,373. The shaft 318 is provided with the gear 320 meshing with the gear 322 pivoted to the frame member 52 as at 324. The gear 322 is non-rotatably provided with the gear 326 meshing with the gear 328 pivoted to the frame member 52 as at 330, and meshing with the gear 332 provided on the cylindrical member 334 similar to the cylindrical member 314.

Power drive mechanism (continued)

The housing members or sleeves 314 and 334 through gears 312 and 332 are journaled on the stop members 336 (Figures 6 and 12) fixed to the side member 52, said stop members being journaled for receiving the shafts 142 and 144. The stop members are provided with the spaced shoulders or stops 338 and 340 spaced 180° apart and adjacent the end surface 342 (Figure 12) of the stop member, the surface 342 being normal to the axes of the shafts 142 and 144.

The ends of the cylindrical housing members 314 and 334 are tapered toward the shaft as at 344 to provide an inner substantially frusto-conical surface for engaging the outer frusto-conical surface of the rotatable stop members 346. The members 346 are urged outwardly of the members 314 and 334 by means of the expansion springs 348, and each of the members 346 is provided with the spring-pressed plungers or pins 350 normally spaced from the ends of the members 336, but when the rotatable stop members 346 are moved inwardly of the members 314 and 334 to compress the springs 348, the pins 350 may engage the shoulder 338. The members 346 are provided with the spaced shoulders or lugs 352 (Fig. 7) which are adapted to engage in the openings or slots 354 provided

in bearing 368 which is provided on the disks or transfer members 356, the disks being rotatably mounted on the shafts 142 and 144. Each of said disks is provided with the transfer tooth 558 adapted to engage the transfer pinion 380 pivoted as at 382 on the carrier 384, the carrier being journaled as at 366 to be mounted on the bearing 368 and being suitably positioned by the shaft 370 (Figure 1). The pinion 380 also engages the gear 372 rotatably mounted on a hub 374 provided on the sprocket 102 (and 110), said hub being provided with the shoulder 376 adapted to engage the transfer tooth 358. The cylindrical portion 194 of the sprocket 102 is provided with the bearing portion or member 378 having the stops 380 corresponding to the stops 340 and 338, and the end 382 of the portion 378 is in a plane normal to the axes of the shafts. In reset position the stops or shoulders 380 are in horizontal alignment with the stops 338 and 340. The gear 384 is rotatably mounted on said bearing portion 378 and is non-rotatably provided with the sleeve 386 similar to the sleeve 314, said sleeve being provided with the internal frusto-conical portion 388 for receiving the rotatable stop member 390 provided with the spring-pressed plunger or pin 392 spaced from the bearing portion 378, but adapted to be moved to engage said bearing portion whereby the plunger 392 may be brought to rest against the shoulder 380, the member 390 being urged away from the bearing portion 378 by means of the spring 394. The member 390 is provided with the spaced shoulders or lugs 393 adapted to engage in the slot 395 of the transfer member or disk 396, said member being provided with the bearing 398 providing a support for the transfer carrier 400.

The transfer carrier is positioned by means of the shaft 370, and is provided with the pinion 402 pivoted to said carrier as at 404, and being adapted to be rotated by means of the transfer tooth 406 on the member 396. The gear 408 also engages said transfer pinion 402, and is rotatably mounted on the hub 410 provided on the sprocket 98 (or 108), said hub being provided with the shoulder 412 adapted to engage the transfer tooth 406. The cylindrical portion 208 of the sprocket 98 is provided with the bearing portion 414 provided with the spaced stops or shoulders 416 similar to the stops 338 and 340, and the gear 418 is rotatably mounted on the bearing 414 and is non-rotatably provided with the sleeve 420 similar to the sleeve 386, being provided with the internal frusto-conical portion 422. As before, in reset position the stops 416 are in horizontal alignment with the stops 380, 338 and 340. The rotatable stop member 424 is disposed within the sleeve 420, being provided with the external frusto-conical surface, and is urged outwardly of the sleeve (i. e., toward the left as viewed in Figure 6) by means of the spring 426, the stop member being provided with the spring-pressed plunger 428 normally spaced from the end 430 of the bearing 414, which end is in a plane normal to the axis of the shaft. Said rotatable stop member 424 is provided with the oppositely disposed shoulders or lugs 432 adapted to be received in corresponding slots 434 provided on the transfer member or disk 436, said slots being provided in the bearing 438 thereof.

The transfer member 436 is also provided with the transfer tooth 440 adapted to be engaged by the shoulder 442 provided on the hub 444 of the

sprocket 92 (or 102). The portion 220 of the sprocket 92 is provided with the helical or sloping surface 446 terminating in the shoulder 448 and being adapted to be engaged by the shoulder or lug 450 provided on the collar 452. The collar 452 is mounted on the sleeve 460 which is secured to the shafts as at 462, and said collar 452 is provided with the diagonal slot 464 for receiving the pin 466 secured to the sleeve 460, the tension spring 468 being provided for normally urging the collar 452 in a clockwise direction, that is, toward the sprocket 92.

The shaft 370 (Figure 1) is provided with the gear 470 meshing with the gear 372, and the gear 470 is non-rotatably connected to the gear 472 through the sleeve 474, the gear 472 meshing with the gear 384. The gear 408 meshes with the gear 476 rotatably mounted on the shaft 370, said gear being non-rotatably connected to the gear 478 through the sleeve 480, the gear 478 meshing with the gear 418. Through similar gearing on shaft 371 (Figure 3) the gears on shaft 144 corresponding to the gears on shaft 142 are properly connected.

Operation

In operation of the form of registering mechanism illustrated in Figures 1 to 15 inclusive, assuming that said mechanism forms a part of a computing head of a liquid dispensing apparatus wherein the variator thereof is driven by the meter and in turn drives the bevel gear 276 in accordance with the setting of the variator, and the bevel gear 316 is driven in accordance with the amount of liquid passing through the meter, the shaft 278 will be driven to cause the upper banks of numeral wheels to compute in money while those in the lower banks of wheels will compute in amount or gallons. Operation of the meter of a liquid dispensing apparatus is effected by passage of liquid therethrough, the liquid being forced therethrough by liquid forcing means and dispensed through the usual hose.

The liquid forcing means may conveniently take the form of a pump operated by means of a motor controlled by the motor switch. The pump motor switch is interlocked with the registering mechanism by a device so constructed and arranged that, having once dispensed liquid and opened the switch, it cannot be closed again until the register has been zeroized.

In the present device, it may be assumed, by way of illustration, that the registering mechanism motor 118 is separate from the pump motor, and that the switch 120 is separate from the motor switch. It is understood, of course, that the pump motor may be used instead of the motor 118, and the switch 120 may be interlocked with the motor switch. In order to dispense liquid the pump motor must be started, and in turn the motor 118 will operate in its forward or registering direction.

When the motor 118 is operating in a forward or registering direction, the switch knob 254 will be conditioned so that the slot 274 will be in the position as shown in Figure 15. The motor shaft 122 will rotate the pinion 124 which will cause rotation of the gear 126. Rotation of the gear 126 will cause the pinion 128 to rotate the gear 130, and consequently the drum 134 will be rotated, causing the belt 136 to rotate the pulleys 138 and 140. Rotation of the pulleys 138 and 140 will rotate the power drive shafts 142 and 144. This rotation will be in a counter-clockwise direction as viewed in Figures 2 and 5. 75

Assuming that the registering mechanism has been zeroized, rotation of the shaft 142 will cause the shoulders 184 and 186 (Figure 10) to engage the ball 190 momentarily in an effort to turn the hub 194 of the sprocket 102, and will cause the shoulders 200 and 214 to engage the balls 204 and 216 momentarily to tend to turn the hubs 208 and 220 of the sprockets 98 and 92. However, this turning movement will not be effected unless the gear 312 is rotated. The shaft 278, which is driven by the variator, will move in accordance with the movement of the variator which will rotate the gear 312 through the train 308, 306, 302, 300, 292, 290, 286, 282 and 280. Movement of the gear 312 by the movement of the variator will cause rotation of the sleeve 314 (in a clockwise direction as viewed in Figure 3), which in turn will rotate the member 346. Rotation of the member 346 will cause the lugs 352 to rotate the transfer member 356, and rotation of said transfer member will cause the tooth 358 to rotate the pinion 360 a predetermined amount for every 360° of rotation of the member 356, it being seen that the tooth 358 engages the long teeth of the transfer pinion 360. Rotation of the transfer pinion 360 by the tooth 358 will cause a corresponding rotation of the gear 372 through the short and long teeth of the pinion 360. 30

The sprocket 102 will rotate in accordance with rotation of the gear 312, as the shoulder 376 will follow in back of the tooth 358, and consequently the lugs 352, by the action of the power drive, that is, by rotation of the shaft 142, permitting forward rotative movement of the hub of the sprocket 102. In other words, it will be seen that the shaft 142 is power driven by the motor 118 in a clockwise direction as viewed in Figure 3 (in the direction of the arrow labelled "Registering direction" in Figure 12), and said shaft will be driven faster than the variator will drive the gear 312. Thus the shoulders 184 and 186 will tend to drive the sprocket 102 faster than the transfer member 356 is driven but the tooth 358 will prevent this as it will be engaged by the shoulder 376 so that the variator in effect acts as a regulator for the forward or registering direction (as shown by the Registering direction arrow in Figure 12) of the sprocket 102. 35

50 and consequently the numeral wheels driven thereby. This retarding movement is permitted as the shoulders 184 and 186 can move past the ball 190 (Figure 10), but they always urge said hub 194 in a clockwise direction in so passing. Rotation of the gear 372 will rotate the gears 470 and 472 (Figure 1), which in turn will rotate the gear 384, causing rotation of the sleeve 386. Rotation of the sleeve 386 will cause rotation of the member 390, which in turn will cause the lugs 393 to rotate the transfer member 396 through engagement of said lugs with the slot 395. Rotation of the member 396 will cause the tooth 406 to rotate the pinion 402 a predetermined amount in 360° of rotation of the member 396, through the long teeth of said pinion, which will cause the gear 408 to be rotated a predetermined amount through the short and long teeth of the pinion 402. The power drive mechanism then (i. e., during rotation of gear 312) will cause rotation of the sprocket 98, as the shoulder 200 will cause rotation of the hub 208 of the sprocket 98 through the spring pressed ball 204. That is, as the shaft 142 is driven continuously and at a faster rate in a clockwise direction as viewed in Figure 3 (shown by the

Registering direction arrow in Figure 12) than the sprocket 98, the shoulder 290 will be continually passing the ball 204, but in so doing it will be urging the sprocket 98 in a forward or registering direction (clockwise in Figure 3 and as shown by Registering direction arrow in Figure 12). The sprocket however can only move with the transfer member 396 as the shoulder 412 will engage behind the tooth 400 and consequently the numeral wheels driven by the sprocket 98 will be controlled by the variator which drives the gear 312.

Rotation of the gear 400 (by tooth 406 and pinion 402) will cause rotation of the gears 476 and 478 (Figure 1), which in turn will rotate the gear 418. Rotation of the gear 418 will rotate the sleeve 426, which in turn will rotate the stop member 424. Rotation of the member 424 will cause the lugs 432 to rotate the transfer member 436 through the slots 434. The power drive will then cause rotation of the sprocket 92 through engagement of the shoulder 214 with the ball 216 to permit the shoulder 442 in the hub 444 of sprocket 92 to follow in back of the tooth 440. That is, as the shaft 142 is rotated continuously and at a faster rate in a clockwise direction as viewed in Figure 3 (and as shown by the Registering direction arrow in Figure 12) than the sprocket 92, the shoulder 214 will be continually passing the ball 216 but in so doing it will be urging the sprocket 92 in a forward or registering direction (clockwise in Figure 3 and as shown by the Registering direction arrow in Figure 12). The sprocket however can only move with the transfer member 436 as the shoulder 442 will engage behind the tooth 406 and consequently the numeral wheels driven by the sprocket 92 will be controlled by the variator which drives the gear 312. Rotation of the sprockets 102, 98 and 92 will move the chains 100, 96 and 99, which in turn will rotate the numeral wheels 70, 78, 66, 76, 62 and 74 in accordance with the movement of said sprockets.

After the desired amount of liquid has been dispensed and it is desired to dispense a new amount of liquid, the switch knob 254 is rotated to reset position, in which position the leg 262 will engage in the slot 274 as shown in the full line position in Figure 14. When the knob 254 is moved to reset position, the switch 120 will reverse the motor 118 to cause movement of the shafts 142 and 144 to be reversed. Reverse movement of the shafts 142 and 144 will cause the balls 162 and 164 (Figure 5) to move along the paths 158 and 160 of the mazes 154 and 156. This movement of the balls along their respective paths causes the members 146 and 154, and 148 and 156 to be separated, thus causing the shafts 142 and 144 to be bodily moved toward the right as viewed in Figure 4. This movement of the shaft 144 causes engagement between the surface 240 and the leg 244 of the member 246 (Figure 13), disengaging said leg from the slot 274. Said movement of the shaft 144, however, disengages the surface 242 from the leg 256 of the member 258, permitting the leg 262 to engage in the slot 274 whereby said slot takes the dotted line position, as viewed in Figure 14. In this position, however, the switch 120 is still closed to reverse the motor 118.

When the balls 162 and 164 have returned to their initial positions, the springs 228 and 230 will move the shafts 142 and 144 toward the left, as viewed in Figure 4, whereupon the surface 242

will engage the leg 256 of the member 258 to release the leg 260 from engagement in the slot 274, so that the spring 272 will move the shaft 266 to permit the slot 274 to move to the position shown in Figure 15. In this position the switch 120 will be conditioned to drive the motor 118 in a forward direction where dispensing operation can again be effected, as described.

Reversing the motor to reverse the movement of the shafts 142 and 144 causes longitudinal movement of said shafts toward the right, as viewed in Figures 4 and 6, as before pointed out. This movement of the shafts causes the members 346, 390 and 424 to be moved toward the right, as viewed in Figure 6, against the springs 348, 394 and 426, disconnecting said members from the sleeves 314, 386 and 420.

Reverse rotation of said shafts then causes the shoulder or lug 450 to engage the shoulder 448 to rotate the sprocket 92 in a reverse movement to return the numeral wheels 62 and 74 to zero position. Reverse rotation of the sprocket 92 causes the shoulder 442 to engage the opposite side of the tooth 440 of the transfer member 436, which in turn causes rotation of the member 424 through engagement of the lug 432 and the member 434. This reverse movement of the member 424 will be effected until the pin 428 engages the shoulder 416, at which time the hub 208, and consequently the sprocket 92, will be revolved in a reverse direction.

Reverse rotation of the sprocket 92 will then return the numeral wheels 66 and 76 toward their zero positions. Reverse rotation of the sprocket 92 causes the shoulder 412 to engage the opposite side of the tooth 406 of the transfer member 396, which in turn rotates the member 390 in a reverse direction. The member 390 will be rotated in a reverse direction until the pin 392 engages the shoulder 380. Rotation of the member 378 will then be effected to cause reverse movement of the sprocket 102, which will cause the numeral wheels 70 and 78 to move toward their zero positions. Reverse rotation of the sprocket 102 will cause the shoulder 376 to engage the opposite face of the tooth 358 of the transfer member 356, which in turn will cause reverse rotation of the member 346 until the pin 350 engages the shoulder 338, at which time all of the numeral wheels will be at the zero position.

In the event that the numeral wheels reach the zero position prior to the time that the balls are returned to their zero position, that is, prior to the shifting of the shafts toward the left as viewed in Figures 4 and 6, the shoulder 450 of the member 452 will merely slip by the shoulder 448, winding up the spring 462 a limited amount as determined by the inclined slot 434. At the time the shafts 142 and 144 assume their zero position the shoulder 450 will be separated from and no longer engage the shoulder 448.

While the above description of operation and reset has referred to only one set of banks of numeral wheels (cost) and their associated control means, it is of course understood that the same description applies to the other sets of banks of numeral wheels (amount) and their control means carried by shaft 144. It is also seen that reset of the cost and amount numeral wheels is independent, as said numeral wheels do not have to reach zero simultaneously, due to the construction and arrangement of the automatic reset mechanism.

Registering mechanism—Figures 16 to 27 inclusive

NUMERAL WHEEL MOUNTING

Referring now to the registering mechanism illustrated in Figures 16 to 27 inclusive, said mechanism is provided with the side plates or brackets 500 and 502. The money shafts 504 and 506 are journaled therein above the amount or gallon shafts 508 and 510 also journaled therein. The numeral wheels 512, 514 and 516 are provided for the shaft 504 for indicating money computations which, in the embodiment shown, are, respectively, cents, tens and dollars; and corresponding numeral wheels 518, 520 and 522 are provided on the shaft 506.

Similar numeral wheels, indicated generally at 524, 526 and 528 (Figure 19) are provided on each of the shafts 508 and 510 for indicating amount characteristics, which in the embodiment shown are fractions, units and tens of gallons. The numeral wheels are preferably mounted on the shafts such as indicated in Figures 26 and 27, all of the numeral wheels being mounted in the same manner. For the purposes of illustration, therefore, only one numeral wheel 512 (Figs. 26 and 27) is shown, said numeral wheel being provided with the hub member 530 rotatably journaled on the shaft 504, said hub member being provided with the sprocket 532 non-rotatably mounted on the hub member. The hub member 530 is also provided with the upstanding flange 534 engaging the web of the wheel 512 externally thereof, the washer 536 engaging the web internally thereof and being securely fastened by means of the nut 538. Thus a very firm mounting for the numeral wheels is provided, and one which inherently braces said wheel. The hub member 530 is provided with the equally spaced ball recesses 540, 542 and 544, shown three in number, in which the balls 546 are mounted, spring-pressed as at 548, to engage in a groove 550 provided on the shaft 504. The balls thus provide a frictional mounting, and one which always maintains the wheels in proper alignment. For the purpose of convenience, the sprockets of each of the numeral wheels are all designated by the same numeral 532.

The sleeves 552 and 554 (Figures 17 and 18) are rotatably mounted on the shafts 504 and 510, and are respectively provided with the spaced sprockets 556 and 558, and 560 and 562, respectively, and said sleeves are provided with the spring-pressed pins or plungers 563 adapted to engage the members 564 non-rotatably mounted on the respective shafts 504 and 510, said members having inclined or helical surfaces terminating in the shoulders 566. The shafts 508 and 510 are provided with the sleeves 568 and 570 rotatably mounted on said shafts and being provided with the sprockets 572 and 574, and said sleeves are also provided with spring-pressed plungers 576 engaging the sloping surfaces of the members 578 non-rotatably mounted on said shafts and terminating in the shoulders 580. The shoulders 566 and 580 are adapted to be engaged by the pins 563 and 576 when the registering mechanism is operating in a forward or registering direction. The sprockets 558 and 572 are connected by the chain 582, and the sprockets 562 and 574 are connected by the chain 584. The sprocket 556 is connected by the chain 586 to the sprocket 588 (Figs. 17, 18 and 22) non-rotatably mounted on the upper power drive shaft 590 of the upper power drive mechanism indicated generally at 592. The sprocket 560 is connected through the

chain 594 to the sprocket 596 rotatably mounted as at 598 on the support 500, and being provided with the gear 600 driven by the gear 602 on the lower power drive shaft 604 of the lower power drive mechanism indicated generally at 606.

Drive for power drive mechanism

The lower power drive mechanism 606 is identical to the upper power drive mechanism 592, so it is understood that a description of the upper power drive mechanism corresponds to that of the lower power drive mechanism, except where specifically otherwise noted. In order to provide driving means for the power drive mechanism, 10 the side plate 502 is provided with the supporting bracket 608 (Figs. 16, 17 and 19) on which the motor 610 is supported, said motor in the embodiment shown being an electric motor. The motor is provided with the drive shaft 612 having the 15 sprocket 614 thereon connected by the chain 616 to the sprocket 618 provided on the power drive shaft 590. The power drive shaft 590 is also provided with the sprocket 620 connected through the chain 622 to the sprocket 624 provided on the lower power drive shaft 604. Thus rotation of the motor shaft 612 effects rotation of the power drive mechanisms 592 and 606. The shafts 590 and 604 are journaled in the side plates 500 and 502 as at 626 and 628 (Figure 22), and said 20 shafts are provided with the collars 630 and 632 having seats for the springs 634 and 636, said springs tending to urge the shafts toward the left as viewed in Figures 19 and 22. The motor shaft rotates in a counterclockwise direction as 25 viewed in Figure 16 during registering operation, and in clockwise direction during reset.

Reset mechanism

Automatic reset mechanism is provided for the 30 shafts 590 and 604, the reset mechanism for the shaft 590 taking the form of a stationary maze member 638 having the helical track 640 therein which extends from a low point 642 (Figures 21 and 22) upwardly from 644 to a shallower track portion 646 which leads into the aperture 648 adjacent the shaft 590. The aperture is then connected with the starting point as through the track or recess 650, said recess being on the side of the member 638 opposite to the helical track 640. The ball 652 is adapted to rotate around 35 said helical track during resetting operation, being urged thereover by means of the plane reset member 654 non-rotatably mounted on the shaft 590. It will be seen that during registering rotation of the member 654, that is, counterclockwise movement, no wear will be had on the ball, as it will be on the low part 642 of the track 640, but during resetting, that is, upon clockwise rotation of the plane member, the ball will be picked up and 40 rotated to the aperture 648, whence it will be returned to the starting point of the track 640 through the aperture 643. During this cycle resetting of the upper banks of registering numeral wheels will be effected.

Automatic reset means for the lower shaft 604 is provided in the form of the stationary maze member 656 (Figures 19 and 21) provided with the spiral track 658 for a similar ball 660, said ball being rotated during resetting operation from 45 a low point 662 of the track 658 up to a higher point, finally being received in the trap 669 adjacent the shaft 604. It will be returned to the starting point through aperture 664, and recess, 50 passage or track 666 disposed on the opposite face of the maze member 656 from the helical track,

said track 666 being connected to the track 658 through the aperture 667. The trap 669 is provided with the platform 673 to which one end of spring 671 is secured as at 675, the platform being below track 658. The spring is slightly above the bottom of aperture 664 so that the ball will not roll into the aperture but must be propelled therein, the spring urging the ball toward the rotating plane member 668. Rotation of the ball is effected through the plane member 668 non-rotatably mounted on the shaft 604. In order to prevent the ball 660 from returning to the starting point of the track 658 prior to the return of the ball 652 to the starting point of the track 640 and thus again initiating the reset cycle, the track 658 (Figs. 21 and 21A) terminates in the offset trap 669 provided with the leaf spring 671 operating to trap the ball 660 during reset, and retaining it until the motion of the shaft 604 is reversed (to its registering direction) at which time the ball 660 is moved to be received in the aperture 664, whereupon it may return to its initial starting position in the track 658 through passage 666.

In order to cause resetting, the reversing switch 670 is provided having the control knob 672. The switch is initially closed to operate the motor in a clockwise or reset direction. The switch is similar to the switch 120 in that having once turned the knob in a clockwise direction to condition the switch for resetting, it will remain in that position until the member 654 unlatches the switch to permit it to return to its normal position by operation of the triggers 674 and 676, said triggers being urged toward each other by means of the spring 680. The maze member 638 is conveniently notched as at 682 to permit ready operation of the trigger 676.

Connections to power drive control mechanism

As before, the shaft 684 (Figures 17, 19 and 20) is journaled in the side plates 500 and 502, and is provided with the bevel gear 686 adapted to be operated in accordance with liquid passing through the meter for indicating gallons or amount, that is, it will be operated by the meter shaft in the case of a liquid dispensing apparatus. Said shaft is provided with the pulley 688 connected through the belt 680 to the pulley 692 mounted on the shaft 510.

The shaft 684 is also provided with the gear 694 (Fig. 20) which meshes with the gear 696 pivoted as at 698 to the side plate 502, said gear being non-rotatably provided with the pinion 700 meshing with the gear 702 pivoted as at 704 to said side plate 502. The gear 702 meshes with the gear 706 rotatably mounted on the lower power drive shaft 604, and said gear 706 meshes with the gear 708 non-rotatably provided on the shaft 710 (Figs. 16 and 20), said shaft extending through the side plate 502 and being provided with the bevel gear 712. The bevel gear 712 meshes with the bevel gear 714 of the amount or gallon totalizer 716.

The shaft 718 for the cost drive is provided with the bevel gear 720 adapted to be driven through the variator which will rotate the shaft 718 in accordance with the setting of said variator. The shaft 718 is provided with the gear 722 meshing with the gear 724 pivotally mounted as at 726 on the side plate 502, and the gear 724 is provided with the bevel gear 728 meshing with the bevel gear 730 non-rotatably mounted on the shaft 732.

The shaft 732 is journaled on the side plate 502 as at 734 and is provided with the bevel gear 736

meshing with the bevel gear 738 pivotally mounted as at 740 on said side plate 502 and provided with the gear 742 meshing with the gear 744, similar to the gear 706, and rotatably mounted on the shaft 590. The gear 744 meshes with the gear 746 non-rotatably provided on the shaft 748 (Figs. 16 and 20). The shaft 748 extends through the side plate 502 and is provided with the bevel gear 750. The bevel gear 750 meshes with the bevel gear 752 for operating the cost totalizer 754.

Lock for the gears 706 and 744

During resetting operation it is desired to positively lock the gears 744 and 706, yet at the same time as soon as the reset operation is effected it is necessary that any locking or braking means used must become inoperative (unlocked) immediately. In order to accomplish this, braking means 756 and 758 are provided. Said braking means includes, respectively, the floating gears 760 and 762 meshing with the gears 744 and 706, and said gears are provided with the disks or rims 764 and 766 of greater diameter than the outside diameter of the gears 760 and 762. Said gears 760 and 762, and the rims 764 and 766 are so disposed that said gears and rims are respectively between the gears 744 and 706, and the inclined planes 768 and 770. The inclined planes are disposed in housings 776 and 778 respectively, secured to the plate 502 adjacent the respective gears 744 and 706.

During registering operation, that is, rotation of the gears 760 and 762, in a counterclockwise direction as viewed in Figure 20, their disks 764 and 766, float between the gears 744 and 706, and the inclined planes 768 and 770 provided in the housings 776 and 778. Upon reversing operation of the motor for reset, the disks 764 and 766 will immediately positively arrest rotation of the gears 744 and 706, and the sleeves 772 and 774 non-rotatably provided on said gears 744 and 706, as said disks wedgingly engage the respective inclined planes 768 and 770, and the gears 760 and 762 engage the gears 744 and 706. This wedging action is caused by counterclockwise rotation of gears 744 and 706 urging gears 760 and 762 downwardly (Figure 20) thereby causing rims 764 and 766 to wedge between their respective inclined planes and sleeves 772 and 774. Upon reversal of the gears 744 and 706 for registering operation, however, the locking means will immediately become inoperative, and the disks and their gears will assume their floating condition.

Connection between the power drive mechanism and the numeral wheels

In order to connect the power drive mechanism with the respective numeral wheels, said power drive mechanism is provided with the sprockets 780, 782 and 784. These sprockets are connected through the chains 785, 786 and 788 to the sprockets 532 provided respectively upon the numeral wheels 512, 514 and 516. Similar connections are made from the corresponding sprockets on the lower power drive 606 to the respective gallon wheels on the shaft 508. In order to connect the numeral wheels on the shaft 506 to the power drive mechanism, a shaft 790 is journaled in the side plates 500 and 502, and is non-rotatably provided with the gear 792 meshing with the gear 794 rotatable with the sprocket 788. The shaft is then non-rotatably provided with the sprocket 796 connected through the chain 798 to the sprocket 532 of the numeral wheel 518. A shaft 800 is also journaled in the side plates 500

and 502, and is non-rotatably provided with the gear 801 meshing with the gear 803 rotatable with the sprocket 784. The shaft 800 is non-rotatably provided with the sprocket 805 connected through the chain 807 to the sprocket 532 of the numeral wheel 522.

A gear 809 is rotatably mounted on the shaft 800 and meshes with the gear 811 rotatable with the sprocket 782, and said gear 809 is non-rotatably provided with the sprocket 813 connected through the chain 815 to the gear 532 of the numeral wheel 520. The lower banks of numeral wheels 524, 526 and 528 mounted on the shaft 510 are similarly connected to sprockets driven by the lower power drive mechanism corresponding with said sprockets or the upper power drive mechanism. The shafts 817 and 819 are provided corresponding to the shafts 790 and 800 for connecting the numeral wheels on the shaft 510 to the power drive mechanism 606.

Power drive mechanism

Referring now to the power drive mechanism (Fig. 22), as before pointed out both the upper and lower power drive mechanisms are similar so a description of one constitutes a description of the other. The sleeve 772 provided on the gear 744 is provided with the internal frusto-conical surface 802 having cooperative relation with the outer frusto-conical surface of the member 804, said member 804 being urged toward the left as viewed in Figure 22 by the spring 806. The member 804 is recessed for the reception of the spring 808 which engages the rotary stop member 810. The rotary stop member 810 is interlocked with the sleeve 812 rotatably provided on the shaft 590 in a manner to be more particularly described with respect to Figure 24, and the member 810 is provided with the stop lug or shoulder 814 adapted to engage the fixed stop pin 816 during resetting movement, as will be later described. While the member 810 is interlocked with the member 812, it is only interlocked in that it rotates with the member 812. However, it reciprocates with respect to said member 812 during reset.

The member 804 is provided with the spaced lugs 818 adapted to engage complementary lugs 820 provided on the hub 822 on which the gear 794 is non-rotatably mounted. The hub 822 is rotatable with respect to the shaft 590 and the sprocket 780. The transfer disk 826 is also non-rotatably mounted on the hub 822. Said transfer disk is provided with the pin 828 corresponding to the pin 816, and said disk is provided with the transfer tooth 830. The gear 832 is rotatably mounted with respect to the shaft 590 and is provided with the sleeve 834, said sleeve forming a convenient bearing for the transfer gear carrier 836 having a bifurcated portion 838 embracing the shaft 790 for positioning said carrier, said carrier having the transfer gear or pinion 840 pivoted thereon as at 842 and provided with alternate short and long teeth engaging the gear 832, the tooth 830 of the disk 826 being adapted to rotate the gear 840 a predetermined amount, and consequently the gear 832 upon every revolution of the disk 826, by engagement of the tooth 830 with the long teeth of the gear 840.

The sleeve 834 is provided with the internal conical surface 844 adapted to engage a corresponding conical surface of the member 846, corresponding to the member 804. The sleeve 848, corresponding to the sleeve 812, is also provided within the sleeve 834. The stop member 850, corresponding to the stop member 810, is urged to-

ward the right as viewed in Figure 22 by the spring 852 corresponding to the spring 808, and the member 846 is urged toward the left as viewed in said figure by the spring 854 corresponding to the spring 806, the member 850 being provided with the stop lug 855 corresponding to the stop lug 814 for engaging the pin 828 during reset. The members 850 and 848 are interlocked against rotation, but are movable axially with respect to each other, as will be more particularly described with respect to Figure 24. The member 846 is provided with the spaced shoulders 858 adapted to be engaged by the complementary shoulders 860 provided on the hub 864. The gear 811, the sprocket 782, and the transfer disk 866 are non-rotatably mounted on the hub 864 which is rotatably mounted on shaft 590. The transfer disk 866 is provided with the stop pin 868 corresponding to the stop pins 828 and 816, and said disk is provided with the transfer tooth 870 engaging the pinion 872 pivotally mounted as at 874 on the carrier 876. The pinion 872 is provided with alternate long and short teeth similar to the pinion 840. The carrier 876 is provided with the bifurcated portion 878 (Figure 23) engaging the shaft 790 for positioning said carrier. The teeth of the pinion 872 engage the gear 830 non-rotatably provided with the sleeve 882, and the tooth 870, upon every revolution of the disk 866, causes a predetermined rotation of the pinion 872 by engagement with the long teeth of said pinion.

The sleeve 884 is rotatably mounted on the shaft 590 and is provided with the shoulders 886 interlocking with the shoulders 888 of the member 890, the member 890 being provided with the stop lug 892 on one of the shoulders 888 adapted to engage the pin 868 during resetting. The shoulders 886 so interlock with the shoulders 888 that movement of translation is permitted but movement of rotation is prevented (Figure 24). The member 890 is urged toward the right as viewed in Figure 22 by means of the spring 894, and the member 896 is urged toward the left as viewed in said figure by means of the spring 898. The member 896 is provided with the spaced shoulders 900 adapted to engage corresponding shoulders on the gear 803, and similar shoulders on the hub 802. The gear 803, the sprocket 784, and the disk 906 are non-rotatably mounted on said hub 902, and the disk 906 is provided with the shoulders 908 spaced 180° apart. The spring 910 abuts against the disk 906 and is disposed in a housing in the sleeve 912 pinned to the shaft, said sleeve 912 being provided with the sprocket 588, and with the stop shoulder 914 on collar 916, which shoulder is adapted to engage a shoulder 908 during reset.

The collar 916 is loosely mounted on the sleeve 912 and is provided with the spaced lugs 918 for the reception of corresponding lugs 920 on the tension adjusting member 924. The adjustable member 924 is provided with the spring 926, one end of which is anchored thereto, the other end being anchored to the fixed member 928. By rotating the member 924 an adjustment can be made of the collar 916 which is slidable on the sleeve 912 by engagement against the lugs 908 of the member 906 after the power drive mechanism has been zeroized. The member 916 is provided with the slot 930 into which the positioning and limiting pin 932 fits, said pin being carried on the member 912. Thus, by adjustment of the member 924 it is possible to determine or set up the degree of force necessary to move the member 916 with respect to the pin 932.

Operation

In operation of the registering mechanism illustrated in Figures 16 to 27 inclusive, assuming that the register has been reset to zero when it is desired to dispense liquid, as before the motor switch is closed and also the switch to the motor 610. Liquid dispensed will cause operation of the meter, which in turn will operate the variator. Rotation of the motor shaft 612 will cause rotation of the sprocket 614, which will rotate the shafts 590 and 604. However, there will be no rotation of the numeral wheels until the meter shaft is operated to cause rotation of the variator and gears 744 and 706.

Rotation of the money and amount take-off gears of the variator will cause rotation of the shafts 718 and 684, shaft 718 being operated through the variator and shaft 684 rotating in accordance with the amount of liquid passing through the meter, that is, in accordance with the rotation of the meter shaft. Rotation of the money drive through the variator will rotate the shaft 718, which will rotate the gear 744 through the gear train 722, 724, 728, 730, 735, 738 and 742. Rotation of the amount portion of the register will be effected through the gear 706 (corresponding to the gear 744) through the gear train 702, 700, 696 and 694.

It is understood that operation of the upper power drive mechanism is similar to that of the lower power drive mechanism so it will only be necessary to describe the operation of one of said shafts, and similar numbers designate corresponding parts. Rotation of the gear 744 (Fig. 22) will cause rotation of the sleeve 772, which in turn will cause rotation of the member 894 as it is urged toward the left by the spring 806. Rotation of the member 894 causes rotation of the gear 794 with the sprocket 780. The sprocket 780 operates the chain 785 to rotate the numeral wheel 512. Rotation of the gear 794 rotates the gear 792 and the shaft 790, which in turn rotates the sprocket 796, causing the chain 798 to rotate the numeral wheel 513.

Rotation of the sprocket 780 causes rotation of the transfer member 826, causing the tooth 830 to rotate the transfer pinion 840 a predetermined amount through the long teeth of said pinion, which in turn rotates the gear 832 through the long and short teeth of said pinion. Rotation of the gear 832 causes rotation of the sleeve 834, which in turn rotates the member 846. Rotation of the member 846 causes rotation of the gear 811, which in turn rotates the sprocket 782, which is non-rotatably mounted on the hub 864 for the gear 811. Rotation of the sprocket 782 causes the chain 786 to rotate the numeral wheel 514 in accordance with the rotation of said sprocket. Rotation of the gear 811 causes rotation of the gear 809, which causes rotation of the sprocket 813, which in turn causes rotation of the numeral wheel 520 through the chain 815.

The transfer member 866 rotates with the sprocket 782, and the tooth 870 rotates the pinion 872 a predetermined amount with every revolution of said transfer member through engagement between the tooth 870 and the long teeth of the pinion. The pinion 872 causes rotation of the gear 830 through the long and short teeth of said pinion, which rotation in turn causes rotation of the sleeve 882. Rotation of the sleeve 882 rotates the member 896, which causes rotation of the gear 803. Rotation of the gear 803 causes rotation of the sprocket 784, which ro-

tates the numeral wheel 516 through the chain 788. Rotation of the gear 803 causes rotation of the gear 801, which in turn causes rotation of the sprocket 805 through the shaft 800, and the numeral wheel 522 is rotated by said sprocket 805 through the chain 807.

After the desired registration is made and it is desired to dispense another predetermined amount, the switch member 672 is rotated to reverse position, causing reverse movement of the motor shaft 612. Reverse rotation of the shaft 612 causes reverse rotation of the shafts 590 and 604. As before, the balls 652 and 660 will move along their predetermined paths 640 and 658 in their respective mazes 638 and 656 until they are returned through the paths 650 and 666 to the initial positions, at which time the register will have been zeroized.

During the movement of the balls the members 654 and 668 will have moved toward the right, as viewed in Figures 19 and 22, causing similar movement of the shafts 590 and 604 against the springs 634 and 636. When the shafts move toward the right as viewed in Figures 19 and 22, the shoulder 914 will engage one of the shoulders 908, causing rotation of the member 906. Rotation of the member 902 through the member 906 causes rotation of the member 884, which in turn causes rotation of the member 890 through the shoulders 888 and 886 (Figure 24). Rotation of the member 890 causes the shoulder 892 to engage the projection 868, which in turn causes rotation of the member 866, and consequently the member 864. The member 864 causes rotation of the member 848, and consequently the member 850 through the shoulders, similar to the shoulders 886 and 888.

The member 850 will rotate until the shoulder 856 engages the pin 828, which in turn rotates the members 826 and 822 in a reverse direction, picking up the member 810 through the member 812 through the shoulders corresponding to the shoulders 886 and 888, until the member 814 engages the stop 816 at which time all of the numeral wheels are in zero position. If the ball controlling the longitudinal movement of the shaft 590 has not returned to its initial position, the reverse movement of the motor will rotate the sprocket 588 and consequently the member 916, but the shoulder 914 will break from the shoulder 908 by virtue of the pin and slot connection 930 and 932, until such time as the members 654 and 638 again engage, at which time the shaft 590 will have moved toward the left as viewed in Figures 19 and 22, permitting the spring 910 to separate the shoulder 914 from the shoulder 908, at which time the switch will be reversed, reversing the motor, and the device will be conditioned for registering.

In this form of the device, the action of the switch 670 is similar to that shown and described in Figures 1 to 15 inclusive. It will further be noted that due to the rotation of the shafts 504, 506, 503 and 510 by the belt 690, the numeral wheels will always tend to be led, and no load (i. e., pushing load) is placed on the variator. This belt can be removed, however, and only a slight load will then be placed on the variator, this load being far less than if the entire register were driven by the variator.

Meter power drive—Figures 28 to 31 inclusive

Referring now to the construction illustrated in Figures 28 to 31 inclusive, a form of mechanism is shown wherein a meter power drive is

contemplated, or a power drive in which the power is furnished from the shaft connected around the variator in a liquid dispensing apparatus. In this construction the variator is indicated at 1000. Said variator is substantially as shown and described in Patent No. 2,323,373, granted July 6, 1943, titled Registering mechanism and computing device, wherein the meter drive shaft 1002 is provided, and a plurality (shown three) of adjusting or calibrating rings 1004, 1006 and 1008 is provided for selectively changing the price at which the variator is set to compute. The amount or gallons take-off (not shown) is also conveniently made from the variator.

For the purposes of this illustration, the shaft 1002 can be considered as the meter shaft, the computing head shown being adapted for use in a liquid dispensing apparatus. As described in said Patent No. 2,323,373, the daily price wheels are indicated at 1010 and 1012, being operated by the setting of the variator. The registering mechanism, indicated generally at 1014, is similar to that described herein, wherein the upper shafts 1016 and 1018 are adapted to mount the numeral wheels indicating the cost of the dispensed liquid, and the lower shafts 1020 and 1022 mount the numeral wheels showing the amount dispensed.

The connecting chains or belts 1024 and 1026 correspond to the chains 584 and 582. In this case the connections between the variator and the registering shafts are similar to that already described. However, in order to furnish power for the power drives, the meter shaft 1002 is adapted to rotate the gear 1028, said gear meshing with the gear 1030 provided on the shaft 1032. The shaft 1032 is journaled as at 1034 and 1036 in the supporting frame 1038, and is provided with the bevel gear 1040. The bevel gear 1040 meshes with the bevel gear 1042 mounted on the shaft 1044, said shaft being provided with the sprocket 1046 receiving the chain 1048 connected to the sprocket 1050 provided on the shaft 1028. The shaft 1044 is also provided with the gear 1052 meshing with the gear 1054 mounted on the shaft 1056 provided with the sprocket 1058, said sprocket being connected by the chain 1060 to the sprocket 1062 provided on the shaft 1022. Thus, in this type of mechanism, power is furnished through the shaft 1002, which furnishes power for the power drive through the gear 1030, shaft 1032, bevel gear 1042, through the respective shafts 1016, 1018, 1020 and 1022. The drive through the variator is transmitted to the power drive in a manner already described.

Reset mechanism

The reset gears 1064 and 1066 are provided for the upper and lower power drive mechanisms indicated generally at 592 and 606, said gears meshing with the gear 1068 provided on the reset shaft 1070, said reset shaft being provided with the usual reset crank 1072. The gear 1068 is provided with the spaced pins 1074 and 1076 located substantially 180° apart, and adapted to engage the yoke 1078 pivoted as at 1080, the yoke being urged downwardly by means of the spring 1082. The upper and lower power drive mechanisms are provided with the stationary mazes 1084 and 1086 corresponding substantially to those indicated at 638 or 656. Figure 30 shows the upper maze, said maze being provided with the track 1087 corresponding to the track 640, and said maze additionally is provided with the spring-pressed pin

5

1088. The plane rotary members 1090 for the mazes are adapted to be rotated by the gears 1064 or 1066, and are provided with the oppositely spaced shoulders 1092 and 1094.

Reset operation

In order to reset the device to zero, the crank 1072 is rotated, causing the balls 1096 to travel around the tracks, and in so travelling they climb from the initial low spot to a higher position in the track separating the members 1090 and 1084, and 1090 and 1086, so that the pin 1088 is cleared by the shoulders 1092 and 1094 and the shafts 590 and 604 are moved longitudinally. When the balls drop or reach the central opening 1102, however, the usual springs corresponding to the spring 634 return the plane members 1090 to engagement with the members 1084 and 1086 so that the pins 1088 will contact the shoulder 1094 to arrest the movement of the operating handle. In this position the pin 1074 or 1076 will have raised the yoke 1078, and upon release of the operating handle 1072 the spring 1082 will cause the yoke 1078 to be moved downwardly, returning the handle to its original position, causing the pin 1088 to contact the shoulder 1092, when the device will be ready for dispensing operation.

As before, the mazes are provided with the trap 1098 and the spring 1100 guarding the aperture 1102 leading to the return path 1104 (this is illustrated as applied to maze 1084, Figure 30). The spring 1100 (Figure 30A) is fastened as at 1101 to the platform 1103 disposed below track 1087 but slightly above the bottom of the aperture 1102, the free end of spring 1100 being adjacent the aperture 1102. The trap receives the ball 1096 which engages end 1105 over platform 1103 until reversal of the member 1090, at which time the ball moves to the free end of the spring 1100 and deflects said spring 1100 and is received in the aperture, and returns to its initial starting position in the track 1087 through the path 1104 and aperture 1106, thus insuring the return of both of the shafts 590 and 604 to position, where they are conditioned for registering operation.

Registering mechanism—Figures 32 to 50 inclusive

Referring now to the registering mechanism illustrated in Figures 32 to 49 inclusive, the registering mechanism consists essentially of the spaced side frames 1150 and 1152 to which are secured the side frame members 1154 and 1156 for the daily price synchronizing means, said members being spaced apart and arranged in pairs.

The meter drive shaft 1160 is coupled as at 1160 to the shaft 1162 (Figure 49), journaled in the gear box 1164 (Figures 36 and 49), the upper end of said shaft being provided with a bevel gear 1166. The bevel gear 1166 meshes with the bevel gear 1168 non-rotatably mounted on the horizontal shaft 1170 journaled in the gear box 1164. The shaft 1170 is provided with the gear 1172, meshing with the gear 1174, non-rotatably mounted on the horizontal shaft 1176, likewise journaled in the gear box 1164, said shaft being provided with the gear 1178, meshing with the gear 1180 non-rotatably provided on the horizontal shaft 1182 journaled in the gear box 1164.

The purpose of this gear box is to provide gear means so proportioned that for each gallon delivered there will be eight (8) turns of the meter shaft 1160, and one gallon will be registered by the gallon banks of numeral wheels. The shaft 1182 extends outwardly of the gear box and is

70

75

provided with the spaced gears 1184 and 1186. The gear 1184 meshes with the gear 1188 (Figure 45), non-rotatably mounted on the bearing 1190, said bearing being rotatably mounted on the shaft 1192 and being prevented from moving longitudinally of the shaft by means of the fixed collar 1194. The gear 1188 is provided with the spaced apertures 1196 for receiving the projecting lugs 1198 (Fig. 48) provided on the sleeve 1200, the ends of said lugs being beveled as shown in Figure 48. The lugs 1198 of said sleeve are urged through the apertures 1196 by the spring 1204 (Fig. 45), one end of said spring being seated on said sleeve 1200, and the other end being seated on the spring seat 1206 provided on the bearing 1190. A ratchet is thus formed by the beveled ends of the lugs 1198, and the complementary teeth 1208 provided on the gear hub 1210 of the sprocket 1212 (Figure 45). The hub 1210 is also provided with the gear 1214 meshing with the gear 1216 pivotally mounted on the jack shaft 1218; the gear 1216 being provided with the sprocket 1220.

Variator connection

The gear 1184 (Figure 49) meshes with the gear 1188, and the gear 1186 meshes with the gear 1222 rotatably mounted on the hub 1210, said gear meshing with the gear 1224 (Figure 35), rotatably mounted on the dead shaft 1226, the gear in turn meshing with the drive gear 1228 of the variator 1230, the variator 1230 being mounted on the side-frame 1150 and of the same general character as that shown in said Patent No. 2,323,373, granted July 6, 1943.

The variator, as shown, is provided with the setting rings 1232, 1233 and 1234, said rings, in the embodiment shown, being for the tens of cents, cents, and one-tenths cents. The shaft 1236, with the driving gear 1226, is suitably connected as at 1238 to the amount or gallons totalizer 1239. Suitable locking members 1240, 1241 and 1242 are provided for preventing accidental movement of the setting rings. The variator is provided with the money drive shaft 1244 suitably connected as at 1246 to the money totalizer 1248.

Posted price indicating mechanism

As before, the setting rings are provided with the spaced cut-out or indented portions 1250 (Figure 33) for receiving the balls of the ball chains 1252, 1254 and 1256 (Figures 33 and 49), said chains being held against the indentations of the setting rings by means of the keeper 1258. The chains pass downwardly toward each side of the variator and pass over the pulleys 1260, 1262 and 1264, pivoted as at 1266 to the frame members 1154. The chains pass over the pulleys 1268, 1270 and 1272, pivoted to the frame members 1154 as at 1273, and are received in the tracks 1274, 1276 and 1278 of the posted price indicating numeral wheels 1280, 1282 and 1284, being secured thereto, the numeral wheels being rotatably mounted on the shafts 1286 carried by the frame members 1154. The numeral wheels are spring-loaded, so that they always tend to keep the chains taut.

Registering mechanism drive mechanism

The money drive shaft 1244 from the variator is provided with the gear 1294, meshing with the gear 1296 (Figures 32, 34 and 37), said gear 1296 being rotatably mounted on the fixed shaft 1298 similar to the shaft 1226. The driving mechanisms mounted on the shafts 1298 and 1226 are the same, so it will only be necessary to describe said mechanism as applied to one shaft. In the

embodiment shown in Figure 37, this mechanism is illustrated as applied to the shaft 1298.

The gear 1296 is provided with sleeve 1300, and sleeve 1300 is provided with the clutch face 1302 of substantially $2\frac{1}{2}^{\circ}$ to 3° , and is adapted to be engaged by the complementary face 1304 of the clutch member 1306, said clutch member being slidably mounted on the shaft 1298 and being urged toward clutched position by means of the spring 1308 provided in the sleeve 1300, one end of the spring being seated on the gear 1298, and the other end of the spring being seated on the clutch member 1306. The clutch member 1306 is non-rotatably connected to the sleeve 1309 on which the gear 1310 is non-rotatably mounted, said gear 1310 meshing with the gear 1312 non-rotatably provided on the shaft 1314 (Figs. 32 and 36), said shaft being journaled in the side frames 1150 and 1152, and being provided with the sprocket 1316, the sprocket 1316 being non-rotatably mounted on said shaft and being connected by the chain 1318 to the sprocket 1320 of the tenths numeral wheel 1322 at the lower side of the register as viewed in Figure 32. The numeral wheel 1322 and the numeral wheels 1324 and 1326 are rotatably mounted on the rotatable shaft 1328, in a similar manner as shown and described with respect to Figures 18, 26 and 27, and the numeral wheels 1324 and 1326 are provided with sprockets 1330 and 1332. Similarly, the tenths, units and tens numeral wheels 1334 and 1336 and 1338 are provided with sprockets 1340, 1342 and 1344 and are rotatably mounted on the rotatable shaft 1346. In a similar manner, as will be more particularly described, the gallons numeral wheels are provided with sprockets and are rotatably mounted on their respective rotatable shafts.

The sleeve 1309 is provided with the sprocket 1348 non-rotatably mounted thereon, said sprocket being connected through the chain 1350 to the sprocket 1340 of the tenths numeral wheel 1334. The sleeve 1309 is provided with the locking ring 1352 (Figure 39), said locking ring having a tooth 1354 provided with a projection 1356 on each side thereof, said tooth and projection being adapted to have operative engagement with the teeth of the transfer pinion 1358. The transfer pinion 1358 is pivoted as at 1359 to the support 1360, the support being fixed by providing the bifurcated end 1362 embracing the shaft 1314 for fixing said support.

The transfer pinion 1358 is provided with alternate short and long teeth; the leading edge of the projection 1356 engages a short tooth of the pinion 1358, rotating it so that the following long tooth is permitted to be received in the tooth 1354, rotation being effected by the motor overdrive, whereby the locking ring will permit intermittent rotation of the pinion 1358. The transfer pinion 1358 meshes with the gear 1364 biased by the overdrive and rotatably mounted on the clutch member 1366 conveniently extending through a suitable aperture in the support 1360 and gear 1364 is provided with the clutch sleeve 1368 similar to the clutch sleeve 1300 and rotatable with the gear 1364.

The clutch sleeve 1368 and the clutch member 1366 have complementary faces 1370 and 1372 similar to the faces 1302 and 1304, and the clutch member 1366 is urged toward clutched position by means of the spring 1374, one end of said spring being seated on the gear 1364, and the other end of said spring being seated on the member 1366. The clutch member 1366 is con-

ected to the sleeve 1376, said sleeve being provided with the gear 1378 which meshes with the gear 1380 (Fig. 32) rotatably mounted on the shaft 1382 fixed to the side frames 1150 and 1152. The gear 1380 is provided with the sprocket 1384 connected through the chain 1386 with the sprocket 1330 of the units numeral wheel 1324. The sleeve 1376 is provided with the sprocket 1388 connected through the chain 1390 with the sprocket 1342 of the opposite units numeral wheel 1336.

The sleeve 1376 is provided with the locking ring 1392 having a tooth 1396 similar to the tooth 1354, being also provided with a projection similar to the projection 1356, the leading edge of which is adapted to engage the short tooth of the transfer pinion 1398 pivoted as at 1399 to the support 1400, the support 1400 being a fixed support conveniently located by being provided with a bifurcated end 1402 engaging the shaft 1314. The projection of the locking ring therefore rotates the pinion 1398 intermittently as it permits the long teeth of the pinion to fall into the tooth 1396, rotation being effected by the motor overdrive, causing the short and long teeth thereof to permit rotation of the gear 1404 braced by the overdrive and pivotally mounted on the clutch member 1406 similar to the clutch member 1366.

The gear 1404 is non-rotatably provided with the clutch sleeve 1408 similar to the sleeve 1368, being provided with the clutch face 1410, adapted to engage the corresponding face 1412 of the clutch member 1406. The clutch member 1406 is urged to clutched position by means of the spring 1414, one end of said spring being seated on the gear 1404, and the other end being seated on the clutch member 1406.

The clutch member 1406 is connected to the sleeve 1416 non-rotatably provided with the gear 1418, said gear meshing with the gear 1420 (Figs. 32 and 36) non-rotatably mounted on the shaft 1382, said shaft being provided with the sprocket 1422 connected through the chain 1424 to the sprocket 1332 of the tens numeral wheel 1326. The sleeve 1416 is provided with a sprocket 1426 connected through the chain 1428 to the sprocket 1344 of the opposite tens numeral wheel 1338.

The sleeve member 1416 is provided with the reset female engagement member 1430 provided with the spaced projections 1432 (Figures 37 and 41), said projections, during reset, being adapted to be engaged by projections 1434 (Figures 37 and 40) provided on the reset male engagement member 1436, said member being rotatably mounted on the sleeve 1438. The sleeve 1438 forms a seat for the friction clutch 1440 provided between the said male engagement member 1436 and the seat 1442 fixedly mounted on the sleeve 1438. The sleeve 1438 is provided with the projections 1444 interlocked with complementary openings of the washer 1446, said washer being fixedly mounted on the sleeve 1448. The end of the sleeve 1448 adjacent the female member 1430 is closed by means of the fixed washer 1450 engaging the shoulder 1452 of the floating sleeve 1454, the end of the floating sleeve 1454, except during reset, being spaced from the sleeve member 1416. The spring 1456 is disposed between the floating sleeve 1454 and the sleeve 1448, and urges said sleeve 1454 toward the right as viewed in Figure 37 against the washer 1450.

Reset mechanism

The spring 1458 is provided on the sleeve 1448 and is disposed between the sleeve member 1438

and the gear 1460 fixed on the sleeve 1448, the gear 1460 meshing with the reset gear 1462 (Figure 32). The gear 1462 is provided on the shaft 1464 journaled in the frames 1466 and 1152, said shaft being provided with the gear 1468 meshing with the gear 1470 adapted to be rotated by the reset crank 1472 through the coupling 1474, said coupling being pivotally mounted on an extension of the shaft 1298, and being retained thereon as at 1476.

The gear 1460 is provided with the race member 1478 having the plane face 1480 adapted to engage the ball 1482 disposed in the spiral path 1484 (Figure 44) of the stationary race member 1486 provided on the frame member 1466. The race member 1486, as already described, is provided with the spiral track 1484, said spiral track extending from a low or deep point 1488 to a higher or shallower point 1490, whereby, when the ball travels from the low point to the high point, it will cause a relative separation between the members 1478 and 1486, moving the elements on the shaft 1298 toward the right as viewed in Figure 37.

A suitable number of convolutions are provided, terminating with an offset portion 1492, a flat spring 1494 being provided, limited in its upward movement by the lug 1496, whereby upon rotation of the member 1478 the ball is finally rotated to engage the spring 1494 and is retained by said spring until such time as the register is reset. A slight reverse movement of the reset handle 1472 causes the ball to walk away from the spring into the portion 1492 where it falls downwardly into the recess 1495 on the under side of the member 1486, and then rolls to the entrance 1497 of the spiral track 1484.

A fixed race member 1498 for resetting the driving elements of the lower or gallon shaft 1226 is provided which is similar to the fixed race 1486, similar numerals being used to designate the parts thereof, and the movement of the lower revoluble race member 1500 need not be timed in any relation to that of the upper revoluble race member 1478, as the balls of the upper and lower reset mechanism may fall independently, yet the register is not conditioned for registering operation until both balls fall to cause the clutch members of the driving elements on the shafts 1226 and 1298 to be clutched, at which time the register is at zero. No constant reverse movement of the reset crank is necessary to condition the reset races for reset operation.

As before pointed out, the gear 1470 is adapted to be rotated by means of the crank 1472 through the coupling 1474, and the gear 1468 is mounted on the shaft 1464 which drives the gear 1462, meshing with the gear 1460. Similarly the shaft 1464 rotates the gear 1502, meshing with the gear 1504. The gear 1504 is pivotally mounted on the shaft 1506 on which one of the banks of gallons numeral wheels is provided. These numeral wheels are indicated generally at 1508 (Fig. 34) and are shown as three in number to indicate the tens, units and tenths (or fractions) of gallons. These wheels are rotatably mounted on the rotatable shaft 1506 in the same manner as already described and are provided with sprockets. The gear 1504 is provided with the spring loaded pawl 1510 (Figure 50) pivoted thereto as at 1512, and said pawl is adapted to engage a suitable tooth or notch 1514 in the shaft 1506, whereby when the handle 1472 is given a slight reverse movement to condition the reset races, the gear 1504 rotates with respect to the shaft 1506, but

during reset the gear 1504 drives the shaft 1506 as a power drive, that is, in the same direction as it is driven during dispensing or registering operation. By this it is meant that during reset the chains driving the numeral wheels are kept in a taut condition usual to forward or registering operation of the numeral wheels, whereas the numeral wheels are being reset in the reverse direction. Thus no lash or lag is set up during reset which would prevent accurate registry.

Drive connections

To complete the power drive to all of the numeral wheels, the shaft 1506 is provided with the sprocket 1516 connected through the chain 1518 to the sprocket 1520 fixed to the upper numeral wheel shaft 1328. The shaft 1505 is also provided with the sprocket 1522 connected through the chain 1524 to the sprocket 1212. The chain runs over an idler 1526 to space the chain from the shaft 1528, the shaft 1528 (Figs. 32, 35 and 36) corresponding to the shaft 1382.

When the gear 1214 (Figure 45) rotates by the reset or by the power drive, it drives the gear 1216, which in turn rotates the sprocket 1220. Rotation of the sprocket 1220 causes the chain 1530 to rotate the sprocket 1532 non-rotatably mounted on the other gallon shaft 1534 of the gallons numeral wheels 1536 disposed below the upper bank of numeral wheels 1322, 1324 and 1326, being similar thereto, and mounted as already described. The shaft 1534 is provided with a sprocket 1538 connected through the chain 1540 to the sprocket 1542 provided on the shaft 1346. When the device is being power driven by the reset, the gear 1188 (Figure 45) is being held stationary by the gear 1184, and the teeth 1208 cause the teeth 1198 of the collar 1200 to move in and out. When the device is being power driven by the meter or shaft 1158, the gear 1188 of course drives the sprocket 1214, and consequently the power drive. By that time the gear 1222 is being driven by the gear 1186 to cause rotation of the driving mechanism on the shaft 1226 similar to the driving mechanism on the shaft 1298, and said mechanism is connected to the respective gallon wheels by the chains similar to those of the respective and similarly placed money wheels, certain of said gallon chains being indicated at 1561, 1563, 1565, 1530 and 1560 (Figure 36), but it is understood that chains corresponding to each of said chains 1428, 1390, 1350, 1318, 1326 and 1424 (Figure 32) are provided, it also being understood that similar transfer mechanism, as well as cross drive mechanism, is provided for the gallons as well as the money, the shafts 1528 and 1556 corresponding to the shafts 1382 and 1314 respectively.

In order to provide a zero stop, the sleeve 1309 on the shaft 1298, and the sleeve 1558 corresponding to the sleeve 1309, are provided with the stop members 1560 and 1562 (Figures 42 and 43). Said stop members 1560 and 1562 preferably are provided with the spaced flanges 1564 in and between which the shoulders 1566 and 1568 are located. The stop pawls 1570 and 1572 are loosely pivoted on the idler shafts 1314 and 1556, and are urged toward each other by means of the spring 1574. Each of said stop pawls 1570 and 1572 is urged toward the right as viewed in Figure 42 by means of the springs 1576 and 1578 anchored to said pawls and embracing spacing members 1580 and 1582 provided on the shafts 1314 and 1356. The stop pawls are provided with the projecting pins 1584 and 1586 adapted to be

received in the cut-out portions 1566 and 1568, respectively, and when the lowest value money and gallons wheels are in the "zero" position, said pawls assume the position illustrated in Figure 43 wherein the upper projections 1588 and 1590 rest upon the hubs of the stop members 1560 and 1562. The major portion of the stress then is taken by the shafts 1298 and 1226. The pawls remain in the "zero" position as shown in Figure 43 until dispensing operation is initiated, when they ratchet out of zero position by rotation of the stop members 1560 and 1562, as they rotate in a clockwise direction as viewed in Figures 42 and 43.

Operation

In the operation of this form of the device, let it be assumed that the registering mechanism is in zero position, that is, all of the registering numeral wheels have been set to zero. In this position, of course, the pawls 1570 and 1572 are in their zero positions, such as indicated in Figure 43, and the operating mechanisms on the shafts 1298 and 1226 are in fully clutched position as shown in Figure 37.

20 Liquid passing through the meter rotates the meter shaft 1158, causing rotation of the gear 1188 (Figure 45) through the gear 1184 (Figure 49) and the gear train contained in the gear box 1164. Rotation of said gear 1188 rotates the sprocket 1212, which in turn causes rotation of the chain 1524 and the shaft 1506 through the sprocket 1522. Rotation of the shaft 1506 causes rotation of the shaft 1328 through the chain 1518 and the sprockets 1516 and 1520. The gear 1214 also rotates with the sprocket 1212 driving the gear 1216 and the sprocket 1220. Rotation of the sprocket 1220 causes rotation of the shaft 1534 through movement of the sprocket 1532 by the chain 1530. Rotation of the shaft 1534 causes rotation of the shaft 1346 through the chain 1540 and the sprockets 1538 and 1542. Rotation of the numeral wheel shafts is always greater than rotation of the numeral wheels 25 when moving in a registering direction, thus setting up a power drive condition whereby substantially no load is put on the variator.

As the meter shaft rotates, the gear 1224 is rotated to rotate the driving elements on the shaft 1226 and consequently the amount or gallon wheels. Rotation of this gear also causes rotation of the variating mechanism in accordance with the setting thereof through the gear 1228 and the shaft 1236. Operation of the variating mechanism causes rotation of the gear 1296 provided on the shaft 1298, and consequently the driving elements for the money wheels. Inasmuch as the driving elements are the same for both shaft 1298 and shaft 1226, it will be sufficient to describe only the operation of the elements illustrated in Figure 37, which are those supported on the shaft 1298.

Rotation of the gear 1296 rotates the sleeve 1300 (Figure 37), causing rotation of the sleeve 1309 through the clutch member 1306. Rotation of the sleeve 1309 rotates the gear 1310, which in turn rotates the gear 1312 (Figure 32), driving the shaft 1314. Rotation of the shaft 1314 causes rotation of the gear 1316, rotating the tenths numeral wheel 1322 through the chain 1318 and the sprocket 1320. Rotation of the sleeve 1309 also rotates the sprocket 1348 which rotates the tenths numeral wheel 1334 through the chain 1350 and the sprocket 1346.

75 Each revolution of the sleeve 1309 causes the

projection 1356 of the locking ring 1352 to position the transfer pinion 1358, whereby it is rotated by the tooth 1354. Movement of the pinion 1358 through one tooth correspondingly rotates the gear 1364, which in turn drives the clutch member 1366 through the sleeve 1368. The clutch member 1366 rotates the sleeve 1376, in turn rotating the gear 1378. Rotation of the gear 1378 causes rotation of the gear 1380 (Figure 32), which in turn rotates the sprocket 1384 to cause the chain 1386 to correspondingly move the units numeral wheel 1324.

Rotation of the sleeve 1376 also rotates the sprocket 1388, which correspondingly rotates the opposite units numeral wheel 1336 through the chain 1390 and the sprocket 1342. As before, rotation of the sleeve 1376 causes the locking ring 1392 to move the pinion 1398 through one tooth to correspondingly rotate the gear 1404.

Rotation of the gear 1404 causes rotation of the clutch member 1406 through the sleeve 1408. Rotation of the clutch member 1406 causes rotation of the sleeve 1416, rotating the gear 1418. Rotation of the gear 1418 rotates the gear 1420 (Figure 32), which in turn rotates the shaft 1382, rotating the sprocket 1422. Rotation of the sprocket 1422 correspondingly rotates the tens numeral wheel 1326 through the chain 1424 and the sprocket 1332. Rotation of the sleeve 1416 rotates the sprocket 1426, causing the corresponding rotation of the opposite tens numeral wheel 1338 through the chain 1428 and the sprocket 1344.

When the desired amount of commodity is dispensed and movement of the meter shaft is arrested, and it is desired to reset the registering mechanism, it is only necessary to give a slight rotation of the reset crank 1472 in the direction of the slot 1492 (Figure 44) to cause the rotating or plain members 1478 and 1500 to move in a 40 counterclockwise direction as viewed in Figure 44. This will cause the balls to enter the openings 1492 and move to the initial position, that is, to the deepest points in the races 1486 and 1498. The reset shaft can then be rotated in the opposite direction by the reset crank, causing the balls to move along the spiral paths 1488. Movement of the balls along the spiral paths causes relative separation between the members 1478 and 1486 (and 1500 and 1498), thus bodily moving the sleeve 1448 toward the right as viewed in Figure 37, and the corresponding sleeve of the shaft 1226 is similarly moved.

Movement of this sleeve toward the right causes the teeth 1434 to engage the teeth 1432 of 55 the female engagement member 1430. Thus the sleeve 1426 will cause the clutches 1406 and 1408, 1368 and 1366, and 1300 and 1306, to become de-clutched, and the gear 1296 will be prevented from rotating by its frictional engagement with 60 the side frame 1150. Continued rotation of the crank will cause the sprockets to reset the numeral wheels to zero as rotation of the crank is transmitted to the sleeves 1416, 1376 and 1309. Clutch member 1406 and sleeve 1376 have inter-fitting projections similar to projections 1367 and 1311 provided on members 1366 and 1309 (Figures 38 and 39), and when the projections are interlocked the numerals are aligned. That is, when said projections of members 1366 and 1309 70 are interlocked so that members 1366 and 1309 rotate as one, similar numerals of the two lowest order numeral wheels are aligned, and when the projections of members 1406 and 1376 are interlocked so that they rotate as one, similar nu-

merals of the two highest order numeral wheels are aligned. Thus it will be seen that the numeral wheels pick up their zero positions from the higher numeral wheel to the lowest, and in the event the numeral wheels register their zero position prior to the time the balls fall to permit the members 1478 and 1500 to be moved toward the left, as viewed in Figures 37 and 34, to permit the clutches to be reengaged, the clutches 1440 will slip, preventing any undue stress on the mechanism. At the zero position, of course, the pawls 1570 and 1572 (Figures 42 and 43) engage in the notches 1566 and 1568 to arrest movement of the operating elements on the shafts 1298 and 1226.

As before explained, during reset the numeral wheel shafts are being power driven in a registering direction. This keeps the operating chains of the numeral wheels taut so that no slack must be taken up when the device again is rotated in a registering direction as by rotation of the meter shaft 1158. In the event either the money or gallons part of the register is reset ahead of the other part, no difficulty is incurred as it merely waits for the reset of the other. Prior to the time that the numeral wheels reach their zero position, the members 1436, 1444 and the sleeve 1448 (Figure 37) rotate in unison, but after the numeral wheels reach their zero position and are held by the stops 1570 and 1572, the member 1436 is arrested but the sleeve 1448 and the member 1444 continue to rotate until the ball falls. In reset, of course, the meter shaft 1158 is stationary, but this does not interfere with the reset because, while the gear 1188 (Figure 45) is held stationary, no interference is placed in the way of rotation of the member 1210 (Figures 45 to 48 inclusive), as the teeth 1198 merely ratchet out of engagement with the teeth 1208.

Registering mechanism drive mechanism—Figures 51 and 52

In the mechanism illustrated in Figures 51 and 52 means is provided whereby the numeral wheels of the register are returned to a predetermined or zero position through a movement of less than 360°. Although this means is shown as adapted to the mechanism particularly shown and described with respect to Figure 37, it is of course obvious that similar mechanism may be provided adapted to the other drive mechanism disclosed herein. Inasmuch as the means is shown as applied to the drive mechanism illustrated in Figure 37, the same numerals are used to designate the same parts and, except where expressly described, the operation of course is the same.

In this embodiment, the shaft 1298 is provided with the sleeve 1600, said sleeve being non-rotatably provided with the female reset engagement member 1602 corresponding to the member 1430, said member being provided with the projections 1604 corresponding to the projections 1432, said projections during reset being adapted to be engaged by the projections 1434 (Figures 37 and 40) provided on the male reset engagement member 1436. As before, the sprocket 1426 is mounted on the sleeve 1416, said sleeve being rotatably mounted on the sleeve 1600. The clutch members 1406, 1366 and 1306 as well as the sleeves 1376 and 1309 and the gear 1296 are likewise rotatably mounted on the sleeve 1600.

The sleeves 1416, 1376 and 1309 are provided with the pawls or dogs 1606, 1608 and 1610 preferably disposed between the gears 1418, 1378 and 1310 and the adjacent sprockets 1426, 1388 and 1348 being urged toward the sleeve 1600 by means

of the springs 1612, 1614 and 1616. When the drive mechanism is operative to rotate the numeral wheels in a registering direction the pawls 1606, 1608 and 1610 ride on the sleeve 1600 and are spaced from the slots 1618, 1620 and 1622 provided in said sleeve, but when the reset mechanism is operative the reset member 1602 is moved toward the right as viewed in Figure 51, in a manner similar to that described with respect to Figure 37, the member 1602 moving the sleeve 1600 to dispose the slots 1618, 1620 and 1622 in substantial alignment with the respective pawls 1606, 1608 and 1610. Therefore, when the slots register with the pawls they will pick up the respective sleeves 1416, 1376 and 1309 to rotate said sleeves until the numeral wheels reach the predetermined or zero position.

At that time the shoulder 1624 on the sleeve 1600 will contact the stop, shoulder or lug 1628 provided on the stop member 1628. The stop member 1628 is mounted on the shaft 1298 and is provided with the oppositely extending stop or lug 1630 receivable in a slot 1632 provided in the end plate 1150. One end of the spring 1634 is connected with the stop 1630, the opposite end being connected as at 1636 to the end plate 1150, and the sleeve 1600 will rotate until the member 1630 moves from the shoulder 1638 to the limiting shoulder 1640, at which time the clutch 1440 (Fig. 37) will slip until the reset operation of the maze members is completed, at which time the reset member 1602, and consequently the sleeve 1600, will be moved toward the left as viewed in Figure 51, and the spring 1634 will move the stop member 1628 to a position where the stop 1630 contacts the shoulder 1638. This will insure a complete reset cycle in the event the reset is again operated, as the shoulder 1626 will then be out of engagement with the shoulder 1624 in the event the reset is again operated, and can only be reengaged by the rotation of the sleeve 1600 through less than 360°.

It is to be understood that I do not wish to be limited by the exact embodiments of the device shown, which are merely by way of illustration and not limitation, as various and other forms of the device will of course be apparent to those skilled in the art without departing from the spirit of the invention or the scope of the claims.

What is claimed is:

1. In registering mechanism, the combination of indicating means, means for driving said indicating means operatively connected to said indicating means, said second named means including clutches, transfer mechanism between said clutches whereby they are serially operated, said clutches being adapted to be declutched to permit reset of said indicating means, and means tending to drive said indicating means in a registering direction during operation of said indicating means.

2. In registering mechanism, the combination of indicating means, means for driving said indicating means operatively connected to said indicating means, and power drive means tending to drive said indicating means in a registering direction, said power drive means including clutches, said clutches being adapted to be declutched to permit reset of said indicating means, said power drive means also including means operatively connecting said indicating means and said power drive means tending to drive said indicating means in a registering direction during reset.

3. In registering mechanism, the combination of a drive shaft, a rotatable numeral wheel shaft,

numeral wheels frictionally and rotatably mounted on said numeral wheel shaft, driving and driven members, a ratchet connection between said driving and driven members whereby said driving member may drive said driven member in one direction, operative connecting means between said drive shaft and said driving member and between said driven member and said numeral wheel shaft whereby rotation of said drive shaft rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, and driving means between one of said clutch members and said drive shaft.

20 4. In registering mechanism, the combination of a rotatable numeral wheel shaft, numeral wheels frictionally and rotatably mounted on said numeral wheel shaft, driving and driven members, a ratchet connection between said driving and driven members whereby said driving member may drive said driven member in one direction, operative connecting means between said driven member and said numeral wheel shaft whereby said driving member rotates said numeral wheel shaft; a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, and driving means between one of said clutch members and said first named driving member.

45 5. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, and reset mechanism for said numeral wheels, said reset mechanism including an operating member, connecting means between said operating member and said first named driven member whereby reset operation rotates said numeral wheel shaft in the same direction as said driving member, means operable by said operating means for declutching said clutch members, and means operable for causing said operating member to rotate said clutch members and said numeral wheels in a reset direction.

60 6. In registering mechanism, the combination of a rotatable numeral wheel shaft, numeral wheels frictionally and rotatably mounted on said numeral wheel shaft, driving and driven members, a ratchet connection between said driving and driven members whereby said driving

75

member drives said driven member in one direction, operative connecting means between said driven member and said numeral wheel shaft whereby said driving member rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, and reset mechanism for said numeral wheels, said reset mechanism including an operating member, connecting means between said operating member and said first named driven member whereby reset operation rotates said numeral wheel shaft in the same direction as said driving member, means operative by said operating means for declutching said clutch members, means operable for causing said operating member to rotate said clutch members and said numeral wheels in a reset direction, and means operable for causing relative movement between said operating member and clutch members to break the drive when said numeral wheels have been reset to a predetermined position.

7. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, reset mechanism for said numeral wheels, said reset mechanism including an operating member, connecting means between said operating member and said first named driven member whereby reset operation rotates said numeral wheel shaft in the same direction as said driving member, means operative by said operating means for declutching said clutch members, means operable for causing said operating member to rotate said clutch members and said numeral wheels in a reset direction, means for arresting movement of said clutch members when said numeral wheels have reached a predetermined position, and means operable for causing relative movement between said operating member and clutch members to break the drive when said numeral wheels have been reset to said predetermined position.

8. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel

shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, reset mechanism for said numeral wheels, said reset mechanism including an operating member, connecting means between said operating member and said first named driving member whereby reset operation rotates said numeral wheel shaft in the same direction as said driving member, means operative by said operating means for declutching said clutch members, means operable for causing said operating member to rotate said clutch members and said numeral wheels in a reset direction, and means for arresting movement of said clutch members when said numeral wheels have reached a predetermined position.

9. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, reset mechanism for said numeral wheels, said reset mechanism including an operating member, connecting means between said operating member and said first named driven member whereby reset operation rotates said numeral wheel shaft in the same direction as said driving member, means operative by said operating means for declutching said clutch members, said last named means including a fixed race member, a rotary race member adapted to be rotated by said operating member, means for separating said fixed and rotary race members, said fixed race member having means for rendering said last named means inoperative whereby said rotary race member moves towards said fixed race member after a predetermined movement of said operating member, and means operable for causing said operating member to rotate said clutch members and said numeral wheels in a reset direction when said race members are separated.

10. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel shaft, a numeral wheel control shaft, a pair of clutch members for each numeral

wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, reset mechanism for said numeral wheels, said reset mechanism including an operating member, connecting means between said operating member and said first named driven member whereby reset operation rotates said numeral wheel shaft in the same direction as said driving member, means operative by said operating means for declutching said clutch members, said last named means including a fixed race member, a rotary race member adapted to be rotated by said operating member, means for separating said fixed and rotary race members, said fixed race member having means for rendering said last named means inoperative whereby said rotary race member moves towards said fixed race member after a predetermined movement of said operating member, means operable for causing said operating member to rotate said clutch members and said numeral wheels in a reset direction when said race members are separated, and means operable for causing relative movement between said operating member and clutch members to break the drive when said numeral wheels have been reset to a predetermined position.

11. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, reset mechanism for said numeral wheels, said reset mechanism including an operating member, connecting means between said operating member and said first named driven member whereby reset operation rotates said numeral wheel shaft in the same direction as said driving member, means operative by said operating means for declutching said clutch members, said last named means including a fixed race member, a rotary race member adapted to be rotated by said operating member, means for separating said fixed and rotary race members, said fixed race member having means for rendering said last named means inoperative whereby said rotary race member moves towards said fixed race member after a predetermined movement of said operating member, means operable for causing said operating member to rotate said clutch members and said numeral wheels in a reset direction when said race members are separated, and means for arresting movement of said clutch members when said numeral wheels have reached a predetermined position, and means operable for causing rela-

tive movement between said operating member and clutch members to break the drive when said numeral wheels have been reset to said predetermined position.

12. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adjacent numeral wheel, transfer mechanism between pairs of said clutch members, driving means between one of said clutch members and said first named driving member, reset mechanism for said numeral wheels, said reset mechanism including an operating member, connecting means between said operating member and said first named driven member whereby reset operation rotates said numeral wheel shaft in the same direction as said driving member, means operative by said operating means for declutching said clutch members, said last named means including a fixed race member, a rotary race member adapted to be rotated by said operating member, means for separating said fixed and rotary race members, said fixed race member having means for rendering said last named means inoperative whereby said rotary race member moves towards said fixed race member after a predetermined movement of said operating member, means operable for causing said operating member to rotate said clutch members and said numeral wheels in a reset direction when said race members are separated, and means for arresting movement of said clutch members when said numeral wheels have reached a predetermined position.

13. In registering mechanism, the combination of indicating means, means for resetting said indicating means to a predetermined position comprising reset means movable to a predetermined position whereby reset movement of said reset means resets said indicating means, control means for moving said reset means to said predetermined position, said control means including a fixed race member, and an adjacent rotary race member, a helical track in one of said race members, separating means movable in said track by said rotatable race member to space said race members from each other a predetermined amount to thereby move said reset means to said predetermined position.

14. In registering mechanism, the combination of indicating means, means for resetting said indicating means to a predetermined position comprising reset means movable to a predetermined position whereby reset movement of said reset means resets said indicating means, control means for moving said reset means to said predetermined position, said control means including a fixed race member, and an adjacent rotary race member, a helical track in one of said race members, separating means movable in said track by said rotatable race member to space said race members from each other a predetermined

amount to thereby move said reset means to said predetermined position, said track having a starting point and a termination point, said separating means permitting said race members to approach each other when it reaches said termination point.

15. In registering mechanism, the combination of indicating means, means for resetting said indicating means to a predetermined position comprising reset means movable to a predetermined position whereby reset movement of said reset means resets said indicating means, control means for moving said reset means to said predetermined position, said control means including a fixed race member, an adjacent rotary race member, a track in one of said race members, separating means movable in said track by said rotatable race member to space said race members from each other a predetermined amount to thereby move said reset means to said predetermined position, said track having a starting point and a termination point, said separating means permitting said race members to approach each other when it reaches said termination point, and a connection between said starting and termination points for returning said separating means.

16. In registering mechanism, the combination of indicating means, means for resetting said indicating means to a predetermined position comprising reset means movable to a predetermined position whereby reset movement of said reset means resets said indicating means, control means for moving said reset means to said predetermined position, said control means including a fixed race member, an adjacent rotary race member, a track in one of said race members, separating means movable in said track by said rotatable race member to space said race members from each other a predetermined amount to thereby move said reset means to said predetermined position, said track having a starting point and a termination point, said separating means permitting said race members to approach each other when it reaches said termination point, a connection between said starting and termination points for returning said separating means, and means for retaining said separating means at said termination point until movement occurs of said rotary race member in a direction opposite to that required for movement of said separating means from said starting point to said termination point.

17. In registering mechanism, the combination of indicating means, rotatable means controlling said indicating means, said rotatable means rotating in one direction during registering operation of said indicating means and rotatable in the opposite direction during reset, a stop member on said rotatable means, a pawl loosely and pivotally mounted adjacent said stop member and having a portion normally riding on said stop member during registering operation, said portion being received in a complementary portion of said stop member during reset to cause movement of said stop member to cease at a predetermined position of said indicating means.

18. In registering mechanism, the combination of indicating means, rotatable means controlling said indicating means, said rotatable means rotating in one direction during registering operation of said indicating means and rotatable in the opposite direction during reset, a stop member on said rotatable means, a pawl loosely and pivotally mounted adjacent said stop member and having a portion normally riding on said stop member during registering operation, said por-

tion being received in a complementary portion of said stop member during reset to cause movement of said stop member to cease at a predetermined position of said indicating means, said pawl having a portion overlying said stop member and adapted to engage therewith when the said indicating means is in said predetermined position whereby no load is placed on the pivot of said pawl.

- 10 19. In registering mechanism, the combination of indicating means, means to furnish the power to move said indicating means operatively connected thereto, control means for governing the movement of said indicating means, means for operating said control means, said control means including a driving sleeve, a driven sleeve, a clutch member adapted to be driven by said driving sleeve, connecting means between said clutch member and said driven sleeve and said indicating means, and transfer mechanism between said clutch member and said driven sleeve whereby said driven sleeve is rotated a predetermined amount for each revolution of said clutch member.
- 15 20. In registering mechanism, the combination of a driven shaft, a rotatable indicating shaft, indicating means rotatably mounted on said indicating shaft, a motor for rotating said driven shaft and said indicating shaft, control means on said driven shaft, operative connections between said control means and said indicating means, means for driving said control means, operative connections between said driving means and said control means, said control means including spaced pairs of clutch members, said pairs of clutch members being disposed in clutched relation when said drive shaft is operating said control means, transfer mechanism between pairs of said clutch members, reset means, said reset means including a switch for initially reversing said motor, said reset means having movable means for bodily moving said driven shaft, movement of said driven shaft causing said pairs of clutch members to be declutched and connecting clutch members of said pairs of clutch members, means rotatable and movable with said driven shaft for rotating said last named clutch members in a reset direction, stop means for arresting movement of said last named clutch members after said indicating means has reached a predetermined position, means associated with said reset means for returning said driven shaft to its position to drive said indicating means in indicating direction and for clutching said pairs of clutch members, and means between said switch and driven shaft to move said switch from reset position to forward driving position.
- 25 21. In registering mechanism, the combination of a driven shaft, a rotatable indicating shaft, indicating means rotatably mounted on said indicating shaft, a motor for rotating said driven shaft and said indicating shaft, control means on said driven shaft, operative connections between said control means and said indicating means, means for driving said control means, operative connections between said driving means and said control means, said control means including spaced pairs of clutch members, said pairs of clutch members being disposed in clutched relation when said drive shaft is operating said control means, transfer mechanism between pairs of said clutch members, reset means, said reset means including a switch for initially reversing said motor, said reset means having movable means for bodily moving said driven shaft, move-

ment of said driven shaft causing said pairs of clutch members to be declutched and connecting clutch members of said pairs of clutch members, means rotatable and movable with said driven shaft for rotating said last named clutch members in a reset direction, stop means for arresting movement of said last named clutch members after said indicating means has reached a predetermined position, means associated with said reset means for returning said driven shaft to its position to drive said indicating means in indicating direction and for clutching said pairs of clutch members, means between said switch and driven shaft to move said switch from reset position to forward driving position, said last named means including a pair of dogs, one of said dogs holding said switch in reset position and the other being operative after the first is inoperative to hold said switch in driving position, and an abutment member on said driven shaft for controlling the effectiveness of said dogs.

22. In registering mechanism, the combination of a driven shaft, a rotatable indicating shaft, indicating means rotatably mounted on said indicating shaft, a motor for rotating said driven shaft and said indicating shaft, control means on said driven shaft, operative connections between said control means and said indicating means, means for driving said control means, operative connections between said driving means and said control means, said control means including spaced pairs of clutch members, said pairs of clutch members being disposed in clutched relation when said driving means is driving said control means, and transfer mechanism between pairs of said clutch members.

23. In registering mechanism, the combination of a driven shaft, a rotatable indicating shaft, indicating means rotatably mounted on said shaft, a motor for rotating said driven shaft, operative connecting means between said motor and indicating shaft so constructed that when said motor is driving in a registering direction said indicating shaft is rotated, control means on said driven shaft, operative connections between said control means and said indicating means, means for driving said control means, operative connections between said driving means and said control means, said control means including spaced pairs of clutch members, said pairs of clutch members being disposed in clutched relation when said driving means is driving said control means, and transfer mechanism between pairs of said clutch members.

24. In registering mechanism, the combination of a driven shaft, a rotatable indicating shaft, indicating means rotatably mounted on said shaft, a motor for rotating said driven shaft, operative connecting means between said motor and indicating shaft including a ratchet permitting rotation of said indicating shaft in a registering direction, control means on said driven shaft, operative connections between said control means and said indicating means, means for driving said control means, operative connections between said driving means and said control means, said control means including spaced pairs of clutch members, said pairs of clutch members being disposed in clutched relation when said driving means is driving said control means, and transfer mechanism between pairs of said clutch members.

25. In registering mechanism, the combination of a driven shaft, a rotatable indicating shaft, indicating means rotatably mounted on said shaft,

a motor for rotating said driven shaft, operative connecting means between said motor and indicating shaft so constructed that when said motor is driving in a registering direction said indicating shaft is rotated, control means on said driven shaft, operative connections between said control means and said indicating means, means for driving said control means, operative connections between said driving means and said control means, said control means including spaced pairs of clutch members, said pairs of clutch members being disposed in clutched relation when said driving means is driving said control means, transfer mechanism between pairs of said clutch members, reset means, said reset means including a switch for initially reversing said motor, said reset means having movable means for bodily moving said driven shaft, movement of said driven shaft causing said pairs of clutch members to be declutched and connecting clutch members of said pairs of clutch members, means rotatable and movable with said driven shaft for rotating said last named clutch members in a reset direction, stop means for arresting movement of said last named clutch members after said indicating means has reached a predetermined position, means associated with said reset means for returning said driven shaft to its position to drive said indicating means in indicating direction and for clutching said pairs of clutch members, and means between said switch and driven shaft to move said switch from reset position to forward driving position.

26. In registering mechanism, the combination of a driven shaft, a rotatable indicating shaft, indicating means rotatably mounted on said shaft, a motor for rotating said driven shaft, operative connecting means between said motor and indicating shaft including a ratchet permitting rotation of said indicating shaft in a registering direction, control means on said driven shaft, operative connections between said control means and said indicating means, means for driving said control means, operative connections between said driving means and said control means, said control means including spaced pairs of clutch members, said pairs of clutch members being disposed in clutched relation when said driving means is driving said control means, transfer mechanism between pairs of said clutch members, reset means, said reset means including a switch for initially reversing said motor, said reset means having movable means for bodily moving said driven shaft, movement of said driven shaft causing said pairs of clutch members to be declutched and connecting clutch members of said pairs of clutch members, means rotatable and movable with said driven shaft for rotating said last named clutch members in a reset direction, stop means for arresting movement of said last named clutch members after said indicating means has reached a predetermined position, means associated with said reset means for returning said driven shaft to its position to drive said indicating means in indicating direction and for clutching said pairs of clutch members, and means between said switch and driven shaft to move said switch from reset position to forward driving position.

27. In registering mechanism, the combination of a driven shaft, a rotatable indicating shaft, indicating means rotatably mounted on said indicating shaft, a motor for rotating said driven shaft and said indicating shaft, control means on said driven shaft, operative connections be-

tween said control means and said indicating means, means for driving said control means, operative connections between said driving means and said control means, said control means including spaced pairs of clutch members, said pairs of clutch members being disposed in clutched relation when said driving means is driving said control means, transfer mechanism between pairs of said clutch members, reset means, said reset means including a switch for initially reversing said motor, said reset means having movable means for bodily moving said driven shaft, movement of said driven shaft causing said pairs of clutch members to be declutched and connecting clutch members of said pairs of clutch members, means rotatable and movable with said driven shaft for rotating said last named clutch members in a reset direction, stop means for arresting movement of said last named clutch members after said indicating means has reached a predetermined position, and means associated with said reset means for returning said driven shaft to its position to drive said indicating means in indicating direction and for clutching said pairs of clutch members.

28. In registering mechanism, the combination of driven shafts, rotatable indicating shafts, indicating means rotatably mounted on said indicating shafts, a motor for rotating said driven shafts and said indicating shafts, control means on said power drive shaft, operative connections between said control means and said indicating means, means for driving said control means, operative connections between said driving means and said control means, said control means including spaced pairs of clutch members, said pairs of clutch members being disposed in clutched relation when said driving means is driving said control means, transfer mechanism between pairs of said clutch members, reset means, said reset means including a switch for initially reversing said motor, said reset means having movable means for bodily moving said driven shafts, movement of said driven shafts causing said pairs of clutch members to be declutched and connecting certain clutch members of said pairs of clutch members, means rotatable and movable with said driven shafts for rotating said last named clutch members in a reset direction, stop means for arresting movement of said last named clutch members after the indicating means on the indicating shafts have reached a predetermined position, means associated with said reset means for returning said driven shafts to position to drive said indicating means in indicating direction and for clutching said pairs of clutch members, and means between said switch and one of said driven shafts to move said switch from reset position to forward driving position, and means for preventing operation of said switch from reset position to forward driving position until said indicating means have been set to said predetermined position.

29. In registering mechanism, the combination of driven shafts, rotatable indicating shafts, indicating means rotatably mounted on said indicating shafts, a motor for rotating said driven shafts and said indicating shafts, control means on said power drive shaft, operative connections between said control means and said indicating means, means for driving said control means, operative connections between said driving means and said control means, said control means including spaced pairs of clutch members, said pairs of clutch members being disposed in

clutched relation when said driving means is operating said control means, transfer mechanism between pairs of said clutch members, reset means, said reset means including a switch for initially reversing said motor, said reset means having movable means for bodily moving said driven shafts, movement of said driven shafts causing said pairs of clutch members to be declutched and connecting certain clutch members of said pairs of clutch members, means rotatable and movable with said driven shafts for rotating said last named clutch members in a reset direction, stop means for arresting movement of said last named clutch members after the indicating means on the indicating shafts have reached a predetermined position, means associated with said reset means for returning said driven shafts to position to drive said indicating means in indicating direction and for clutching said pairs of clutch members, and means for preventing registering movements of said indicating means until said indicating means have been set to said predetermined position.

30. In registering mechanism, the combination of indicating means, means for driving said indicating means, operative connecting means between said driving means and said indicating means, including clutches, declutching means for declutching said clutches to permit reset of said indicating means, and means movable by said declutching means to cause said indicating means to be reset to a predetermined position by movement through less than 360°.

31. In registering mechanism, the combination of indicating means, means for driving said indicating means, operative connecting means between said driving means and said indicating means, means tending to drive said indicating means in a registering direction, said connecting means including clutches, declutching means for declutching said clutches to permit reset of said indicating means, and means movable by said declutching means to cause said indicating means to be reset to a predetermined position by movement through less than 360°.

32. In registering mechanism, the combination of indicating means, means for driving said indicating means, operative connecting means between said driving means and said indicating means, said connecting means including clutches, transfer mechanism between said clutches whereby they are serially operated, declutching means for declutching said clutches to permit reset of said indicating means, means tending to drive said indicating means in a registering direction during reset, and means movable by said declutching means to cause said indicating means to be reset to a predetermined position by movement through less than 360°.

33. In registering mechanism, the combination of a rotatable numeral wheel shaft, numeral wheels frictionally and rotatably mounted on said numeral wheel shaft, driving and driven members, a ratchet connection between said driving and driven members whereby said driving member drives said driven member in one direction, operative connecting means between said driven member and said numeral wheel shaft whereby said driving member rotates said numeral wheel shaft, a numeral wheel control shaft, a pair of clutch members for each numeral wheel rotatably mounted on said control shaft, one clutch member of each pair being relatively movable with respect to the other clutch member, one clutch member of each pair being connected to its adja-

cent numeral wheel, a stop sleeve, means for connecting said last named clutch members to said sleeve, transfer mechanism between pairs of said clutch members, driving means between one of said clutch members and said first named driving member, reset mechanism for said numeral wheels, said reset mechanism including an operating member, connecting means between said operating member and said first named driven member whereby reset operation rotates said numeral wheel shaft in the same direction as said driving member, means operative by said operating means for declutching said clutch members and causing said stop sleeve to be connected to the last named clutch members, means operable for causing said operating member to rotate said clutch members and said numeral wheels in a reset direction, and means for arresting movement of said stop sleeve and numeral wheels at a predetermined position after said sleeve has rotated in a reset direction through less than 360°.
